POSITIVELY CONTROLLED TUBE BORE
MANDEL FOR TUBE FORMING MACHINES

John B. Wintercorn, Chicago, Ill.

Application June 12, 1934, Serial No. 730,232

17 Claims.

(Cl. 80—13)

My invention relates to improvements in all tube forming machines of that class in general in each of which a tube bore mandrel is employed to form the bore of the tube simultaneously as the usual rollers or die form the outside surface of the tube, while progressively working upon an appropriate blank from which the tube is produced within the pass of the rollers or die, having as a general object the positive control of the tube bore mandrel within the pass throughout the tube forming operation on the blank in each instance, as contrasted with the lack of positive control of the tube bore mandrel within the pass in these machines in the past, for the purpose of improving the accuracy of the location of the bore relative to the outside surface of the tube in each instance as well as lowering the production costs of the tubes, as compared with these factors in tube production by these machines in the past, and relates in particular to these improvements as applied to the disk roller machine for helically rolling seamless tubes, which constitutes the preferred embodiment of my invention as described in detail herein.

Tube forming machines of the described class in the past were not provided with means for positively controlling the tube bore mandrels within the pass of the rollers or the die, and the tube bore mandrel in each instance was allowed to freely "float" laterally within the pass, as well as turn through a considerable angle about the longitudinal axis thereof as permitted by the torsional flexibility of the connected mandrel rod. The latter turning of the tube bore mandrel, was harmful of course only when making tubes having bores of non-circular lateral section, and not for those having circular lateral section. The tube bore mandrel was thus free to locate itself in conformity with the previously formed centering hole indented a short distance within the forward end of the solid blank, in the case of the usual tube piercing mill; and, when this indented hole was traversed by the mandrel, was thereafter controlled only by the irregularly opened core fissure ahead of same within the blank. While, in the case of the usual tube reeling mill, the usual tube rolling mill, and the usual tube drawing bench, the tube bore mandrel was free to locate itself in conformity with the previously formed bore in the tubular blank. This haphazard method of operation of the tube bore mandrels has been the cause, not only of inaccuracy in the location of the bores relative to the outside surfaces of the tubes thus produced, but also of the excessive costs of production, due to

the excessive number of operations required to secure the slight degree of accuracy obtainable, and the incidental spoilage of material accompanying the method. In the employment of the floating type tube bore mandrels, the assumption was made that, for equally distributed balancing forces laterally about the pass, for both the rollers and the die, a familiar law of materials, whereby the rollers or the die would reduce the thicker side more than the diametrically opposite thinner side of the wall of the blank, would be applicable if the number of operations were sufficiently large. However, this law of materials is perfectly effective only for homogeneous materials, of thin rather than thick wall section, and of uniform density and hardness; all of which are contrary to the usual qualities of the material used for making tubes on a commercial basis. Thus, accuracy was not obtainable commercially by means of the floating type tube bore mandrel for the thick walled tubes, and to no appreciable extent for the thin walled tubes of sizes commonly used; though the latter were more accurate due to the larger number of operations thereon, as well as greater effectiveness of the law of materials mentioned with respect thereto. These statements are borne out by published data on tubes made on a commercial basis, the variations in wall thickness being: for thin wall tubes, under ten per cent plus and minus from the nominal wall thickness; for thick wall tubes, from ten to twenty-five per cent plus and minus from the nominal wall thickness; the minus side, or thin side, in each case being diametrically opposite the plus side, or thick side, of the tube considered. Where there was a fair degree of accuracy, the wall thickness of the tubes was exceedingly thin, and the number of operations enormous, with selected expensive material, and all conditions not to be duplicated on a commercial basis.

With the controlled type tube bore mandrels of my invention applied to all these machines, each operation results in a perfectly accurate blank or tube, as the case may be, from the initial tube piercing and reeling operations, through the tube rolling operations to the final tube drawing operations, regardless of whether the wall thickness of the blank or tube is thick or thin, or whether the material is homogeneous or not. No reliance is placed upon the law of materials mentioned above, contrary to what was seen true with the floating type tube bore mandrel; though the law will obviously still be effective and helpful as hitherto. Also, in the case of tubes having non-

circular section bores, there are means provided which maintain the bore of the tube, as it leaves the pass in each case, in alignment with the forming surfaces of the tube bore mandrel within the pass; thus, there can be no relative rotation between the forming surfaces of the tube bore mandrel and the bore of the tube, as prevailed hitherto in the case of the floating type tube bore mandrel, and which rendered accuracy in the relation between the bore and the outside surface of such tubes unattainable with the latter type mandrel. It is therefore clear that the number of operations, with the controlled type tube bore mandrels, will be very much less than formerly with the floating type tube bore mandrels, since the cause for the formerly prevailing excessive number of operations is avoided by the employment of the means of my invention. Likewise, by presenting an accurate blank for each operation, particularly for the drawing operations, spoilage of material will be eliminated, since tearing of the blank walls was formerly due to unequal wall thickness thereof. Production of seamless tubes, by the employment of controlled type tube bore mandrels in all these machines, should therefore be accompanied by lower costs as well as superior accuracy as compared with former costs and accuracy.

While my invention relates to all tube forming machines of the described class, and as such is fully covered by the appended claims, the existing types of tube rolling machines are not considered by me as well adapted to the effective application of my invention thereto as the disk roller machine for helically rolling seamless tubes herein shown and described in detail as the preferred embodiment of same. Several of the new characteristics of seamless tubes, now given as follows, will be seen to be due to the peculiar qualifications of the disk roller machine alone, and not found in the case of applications of my invention to the other machines:

(1) The outside surfaces and bores of all tubes are coaxial, whereby tubes having circular cylindrical outside surfaces and bores have walls of uniform thickness. (2) The outside surfaces and bores of all tubes are perfectly straight longitudinally. (3) The outside surfaces are uniformly circular cylindrical for all tubes, and the bores are uniformly of the form required. (4) The outside surface diameter dimensions are uniform for an indefinite number of tubes, since there is not any appreciable wear of the faces of the disk rollers; and the same is true of the bore dimensions, regardless of whether the bores are cylindrical or non-cylindrical, or are of circular or non-circular lateral sectional form. (5) The material of the walls of all tubes is uniform in density and hardness and in strength, due to the superior rolling action of the disk rollers. (6) The surface finish on all tubes is uniformly smooth, due also to the superior rolling action of the disk rollers.

The characteristics (1) and (2), given above, apply also to tubes made by all other tube forming machines of the described class. In addition, particularly in the case of tubes having the outside surfaces and bores thereof of non-circular lateral section, as, for example, of hexagon lateral section, the apexes of the hexagon section of the outside surface and of the bore will be in radial alignment as required; and for other sections as well, the relation between the sections will be as required, due to the means provided for guiding the bore of the tube in alignment

with the forming surfaces of the tube bore mandrel within the pass, as mentioned before. Since the outside surfaces of tubes helically rolled by the disk roller machine are circular cylindrical in all instances, the additional characteristic of tubes mentioned above applies to tubes made by the other tube rolling machines and the tube drawing bench.

The chief objects of my invention are, to provide in a tube forming machine of the described class:

First, means coaxially adjacent to the pass for positively guiding the outside surface of the tube coaxially with the said pass.

Second, means adjacent to the said pass coaxially connected to the mandrel means for positively guiding the bore of the tube coaxially with the said mandrel means within said pass.

Third, means coaxially connected to said mandrel means and said bore guiding means and tightly coaxial contacting with the said outside surface guiding means adjacent to said pass for positively locating and holding the said mandrel means and said bore guiding means coaxial to each other and respectively coaxial within said pass and to said outside surface guiding means at the start of the tube forming operation, whereby the said outside surface and said bore of said tube are formed coaxial to each other.

Further objects are:

First, to provide the means substantially as herein described, as best adapted for the achievement of the above objects, particularly when applied to narrow-pass machines such as the disk roller machines and the tube drawing bench, and thereby to secure the six improved characteristics in tubes before mentioned.

Second, to permit production of seamless tubes at reduced cost, through reduction in the number of operations, and elimination of spoilage of material, heretofore due to use of the floating type tube bore mandrels.

Third, to permit more economy in the purchase and use of tube material, by permitting the purchase of tubes exactly suitable for given installations by merely specifying the nominal wall thickness required, with full assurance that no failure of tube material in service is possible, as contrasted with the former necessity of purchasing tubes having wall thicknesses of from ten to twenty-five per cent heavier and costlier, due to the former non-uniform wall thickness, in order that the expected thinnest wall sections have sufficient strength, and without any assurance that failure of the tubes in service would not follow, due to the unpredictable conditions of tube production with the floating type tube bore mandrels.

Fourth, to permit extension in the uses of seamless tubes, permitted by reduction in cost and through greater accuracy brought about by my invention, not only for old but also for new applications thereof, such as: tubular shafting, for all power transmission purposes, which require uniform wall thickness for dynamic balance; structural purposes, as frames for airplanes, bicycles, and furniture; machine parts, such as sleeves, bearing bushings, etc.; piping purposes, such as steam piping, compressed air or ammonia piping, oil refinery and other processes in which high pressure piping is used; and also for boiler and condenser tubes.

The tubular blanks, from which the seamless tubes are helically rolled, are prepared in the same manner as in the past.

The materials for the seamless tubes may be the same as hitherto employed, viz., steel, wrought iron, copper, brass, bronze, aluminum, nickel, and various other metals and alloys, to be rolled while at the usual rolling heat, or while cold (ordinary temperature), in accordance with the usual practice with these metals. Many non-metallic materials such as vulcanized fibre of various kinds, vulcanized rubber, Bakelite, and other compositions besides these, may be helically rolled after being made suitably ductile for the purpose.

Seamless tubes may be produced directly from the prepared tubular blanks by the machine of my invention, or may be produced with the intermediate operations, or the final operations, on the blanks performed by the existing tube forming machines, depending upon the kind of tubes being made and their dimensions, as follows:

(1) All tubes having circular cylindrical outside surfaces with the bores of the form described of large enough diameter to permit forming same over a mandrel, as in the past, may be produced directly by the machine of my invention from the prepared tubular blanks; the number of passes depending upon the reduction in wall thickness, the reduction of the outside surface diameter, the reduction of the bore diameter, or both the reduction of the outside surface and the bore diameters.

(2) Tubes having non-circular cylindrical outside surfaces, or tubes having circular cylindrical outside surfaces but of such small diameters as to forbid being formed over a mandrel, are produced by helically rolling the tubular blanks in my machine preliminary to rolling or drawing in the existing tube forming machines to form the finished tubes.

(3) Tubes of circular cylindrical form on both the outside surface and the bore, which require greater speed of handling than is possible by the machine of my invention, such as hot rolled boiler tubes, are produced most efficiently by performing the preliminary and the final passes in my machine and the intermediate passes in the existing types of tube rolling machines.

Besides the disk roller machine for helically rolling seamless tubes, constituting the preferred modification of my invention, the positively controlled tube bore mandrels of my invention may be applied to six other types of tube forming machines later fully described herein.

In the accompanying drawings:

Fig. 1 is a plan view of the disk roller machine for helically rolling seamless tubes, provided with the positively controlled tube bore mandrel, comprising the preferred modification of my invention.

Fig. 2 is an enlarged fragmentary sectional side view, taken along uneven line 2—2—2 in Fig. 1.

Fig. 3 is a sectional end view, taken along line 3—3 in Fig. 2.

Fig. 4 is a fragmentary sectional end view, taken along line 4—4 in Fig. 2.

Fig. 5 is an enlarged end view, taken along line 5—5 in Fig. 1, showing the forward end of the spindle housing.

Fig. 6 is an enlarged end view, taken along line 6—6 in Fig. 1, showing the rear end of the spindle housing.

Fig. 7 is an enlarged fragmentary sectional side view, taken along line 7—7 in Fig. 1, showing in diagrammatic form the essential parts of

the machine involved in helically rolling seamless tubes.

Fig. 8 is a fragmentary sectional end view, taken along line 8—8 in Fig. 7, of the mandrel rod, support bracket, yoke, and collars.

Fig. 9 is an enlarged fragmentary sectional side view, taken along line 9—9 in Fig. 1, showing the start of the tube rolling operation on the tubular blank.

Fig. 10 is a side view of the mandrel locating and holding sleeve, seen in sectional side view in Fig. 9 within the bore of the tube guide bushing and over the forward end extension of the longitudinally stationarily held tube bore mandrel.

Fig. 11 is a fragmentary sectional end view, taken along line 11—11 in Fig. 10, of the mandrel locating and holding sleeve.

Fig. 12 is a fragmentary sectional end view, taken along line 12—12 in Fig. 9, showing the means for locking the mandrel locating and holding sleeve within the bore of the tube guide bushing, as well as the unlocked position thereof during the tube rolling operation.

Fig. 13 is the same as Fig. 9 otherwise, but shows the mandrel locating and holding sleeve being progressively displaced from within the bore of the tube guide bushing and from over the forward end extension of the longitudinally stationarily held tube bore mandrel by the forward end portion of the helically rolled tube during the tube rolling operation on the tubular blank.

Fig. 14 is a sectional end view, taken along line 14—14 in Fig. 13, showing parts related to the tubular blank.

Fig. 15 is a sectional end view, taken along line 15—15 in Fig. 13, showing parts related to the tube.

Fig. 16 is an enlarged side view of a portion of the tubular blank partially helically rolled to form the tube, showing on the outside surface of the tube in diagrammatic form the relation between the helical paths of the tube rolling faces on the disk rollers, the narrow pass being indicated by two lateral lines at the juncture of the tube with the tubular blank from which it is formed, also one of the four disk rollers is shown dotted to illustrate the angular relation between same and the axis of the pass and tube and to show the small contact area for each of the tube rolling faces of the disk rollers.

Fig. 17 shows the relation between the disk roller and the grinding wheel during the operation of grinding the concave tube rolling face of the disk roller.

Fig. 18 is a front view of the disk roller and grinding wheel seen in Fig. 17.

Fig. 19 is an enlarged fragmentary section, taken along radial line 19—19 in Fig. 18, of the disk roller.

Fig. 20 is an enlarged fragmentary end view, taken along line 20—20 in Fig. 13, of the tube guide bushing in the bore of the split bearing of the tube guide bushing carriage, showing the provisions for lubrication of the bore of the tube guide bushing, and the clearance notches in the rear end of the tube guide bushing as well as in the split bearing.

Fig. 21 is a fragmentary sectional side view, taken along line 21—21 in Fig. 20, of the tube guide bushing and the split bearing.

Fig. 22 is a fragmentary section, taken along radial line 22—22 in Fig. 20, of the rear end of the tube guide bushing at one of the projections between clearance notches.

Fig. 23 is an enlarged side view of the longitudinally stationarily held tube bore mandrel, showing provisions for lubrication of the circular cylindrical outside surface thereof, the 5 dotted fragment of one of the disk rollers showing the longitudinal relation between same and the grooves on the mandrel.

Fig. 24 is an end view of the forward end of the mandrel seen in Fig. 23.

10 Fig. 25 is a side view of the longitudinally movable tube bore mandrel, showing the tubular blank in place thereon preparatory to the tube rolling operation, a fragment of one of the four disk rollers being shown (dotted) to indicate the 15 relation to the replaceable mandrel locating and holding sleeve (in section) on the forward end shank of the mandrel at the start of the rolling operation.

15 Fig. 26 is an end view at the shank end in Fig. 25.

20 Fig. 27 is an end view at the mandrel end in Fig. 25.

25 Fig. 28 is a fragmentary sectional plan view of the disk roller machine for planetarily cross rolling seamless tubes, provided with the positively controlled tube bore mandrel, in which the spindle housing with disk rollers is rotated at a fixed 30 location, and the tubular blank is fed longitudinally forward through the pass of the disk rollers by auxiliary feeding means, comprising a second modification of my invention.

35 Fig. 29 is a fragmentary sectional plan view of another disk roller machine for planetarily cross rolling seamless tubes, provided with the positively controlled tube bore mandrel, in which the spindle housing with disk rollers is rotatably mounted on a slidably mounted carriage adapted to be longitudinally moved over machine ways, and the tubular blank is held in fixed position 40 while the pass of the disk rollers is caused to be moved longitudinally thereover as the carriage is longitudinally moved over the machine ways by the actuating means therefor, comprising a third modification of my invention.

45 Fig. 30 is a fragmentary sectional side view, taken along the axis 210—210 in Figs. 28-29, showing the modification of the positively controlled tube bore mandrel required for rolling cupped-end tubular blanks in the disk roller machines seen in Figs. 28-29, as applied particularly to a stationary type mandrel. A universal joint connection between the mandrel and mandrel rod is shown.

50 Fig. 31 is a fragmentary sectional side view of the positively controlled tube bore mandrel as applied to the otherwise usual tube drawing bench, showing the modified die head having the drawing die and tube guide bushing assembled therein, and the stationary type mandrel for 55 drawing cupped-end tubular blanks, the latter being in all respects identical with the mandrel seen in Fig. 30, comprising a fourth modification of my invention.

60 Fig. 32 is a fragmentary sectional side view of the positively controlled tube bore mandrel as applied to the otherwise usual grooved roll tube rolling machine, showing also a sectional end view of two of the grooved rolls, and the stationary type mandrel and other details similar 65 to those shown in Figs. 1-13, comprising a fifth modification of my invention.

65 Fig. 33 is a fragmentary sectional plan view of the positively controlled tube bore mandrel for tube piercing as applied to the otherwise usual 70 so-called Stiefel tube piercing and reeling mill,

showing also a plan view of the two rolls of the mill, comprising a sixth modification of my invention.

Fig. 34 is a sectional view taken along line 34—34 in Fig. 33, showing the roll-clearance 5 notches and the projections between the rolls of the rear end of the tube guide bushing in Fig. 33 similar to those seen in Figs. 20-21.

Fig. 35 is a fragmentary sectional plan view of the positively controlled tube bore mandrel 10 for tube piercing as applied to the otherwise usual so-called Mannesmann tube piercing and reeling mill, showing also a plan view of the two rolls of the mill, comprising a seventh modification 15 of my invention.

Fig. 36 is a sectional view taken along line 36—36 in Fig. 35, showing the roll-clearance 20 notches and the projections between the rolls of the rear end of the tube guide bushing in Fig. 35 similar to those seen in Figs. 20-21.

Referring now to the drawings:

In Fig 1 is seen the tubular blank 1, having outside surface 2 and bore 3, to the left or rear end of the machine with respect to the disk rollers 8, and the helically rolled portion of the blank 25 1 forming the tube 4, having outside surface 5 and bore 6, to the right or forward end of the machine with respect to the disk rollers 8. The portion of the blank 1 has been helically rolled to form the tube 4 after passing between the 30 conical faces 7 and through the pass 24 of the tube rolling faces 8 of the four disk rollers 9 and over the circular cylindrical outside surface 10 of the longitudinally stationarily held tube bore mandrel 11 longitudinally within the pass 24, 35 from left to right as indicated by the horizontal arrows. After passing the four disk rollers 9, the outside surface 5 and the bore 6 of the tube 4, respectively, passes through the bore 12 of the tube guide bushing 13, and over the forward 40 end extension of the outside surface 10 of mandrel 11 within the bore 12 of bushing 13. The four disk rollers 9 are individually removably rigidly mounted upon and rotatably driven by the four spindles 14, as best seen in Figs. 2-7, and 45 the latter are individually rotatably mounted in the forward bearing bushings 15 and the rear bearing bushings 16 in eccentrically located bores 17 in the four eccentric sleeves 18, only one eccentric sleeve 18 being seen here. Each sleeve 50 18 has a worm gear 19 integral therewith at the rear end thereof coaxial with the circular cylindrical outside surface 20 thereof, as seen in Fig. 2, and each worm gear 19 meshes with a worm 21. The four worms 21 have each an integral square 55 end shaft 22, adapted to receive a crank handle (not shown), axially projecting from one end and a plain shaft 22' projecting from the opposite end, to permit individually manually rotating same and thereby the worm gears 19 and the 60 sleeves 18 when making radial adjustments individually of the tube rolling faces 8 of the disk rollers 9 relative to the longitudinal axis 23—23 of the pass 24 of the faces 8. The four eccentric sleeves 18 are rotatably mounted in four bores 65 25 in the spindle housing 26, the bores 25 being laterally equally spaced about the longitudinal axis 23—23 of the pass 24 (see Fig. 5) coinciding with the longitudinal axis of the bore 12 of the tube guide bushing 13 and of the tube bore mandrel 11. The longitudinal axis 27—27 of each of the four bores 25, coinciding in each instance with the axis 28—28 of the outside surface 20 of each eccentric sleeve 18 rotatably mounted 70 therein, is at the same angle 29 with the longi-

75 75

tudinal axis 23—23 of the pass 24. In each of the four eccentric sleeves 18, the longitudinal axis 30—30 of the eccentrically located bore 17 is parallel to the longitudinal axis 28—28 of the outside surface 20 thereof, being separated by a distance equal to the eccentricity 31. Thus, when radial adjustments of the tube rolling faces 8 of the disk rollers 9 are being made relative to the longitudinal axis 23—23 of the pass 24, each 10 of the four eccentric sleeves 18 is individually rotated (by means of worm gear 19 and worm 21 and square end shaft 22 and crank handle) about its longitudinal axis 28—28 of the outside surface 20 thereof to secure a radial adjustment 15 of each individual tube rolling face 8 equal in amount within the limits of two times the eccentricity 31, as best seen in Figs. 2—4, and collectively for all the tube rolling faces 8 within the limits of four times the eccentricity 31. The 20 tube rolling diameter capacity range of the set of four disk rollers 9, each having the same diameter dimension of the tube rolling face 8, extends from the minimum diameter of the outside surface 5 of the tube 4 to the maximum diameter 25 of the outside surface 5 of the tube 4, the latter maximum diameter being equal to the minimum diameter plus four times the eccentricity 31. By employing a number of different sets of the four disk rollers 9, each individual set having its 30 individual diameter dimension of the tube rolling faces 8 different from those of the remaining sets and varying successively in an ascending order by four times the eccentricity 31, the set with the smallest diameter dimension of the tube 35 rolling faces 8 is adapted to roll the largest diameter of the outside surface 5 of the tube 4 within the diameter capacity range of the machine, and the set with the largest diameter dimension of the tube rolling faces 8 is adapted 40 to roll the smallest diameter of the outside surface 5 of the tube 4 within the diameter capacity range of the machine, with intermediate sets with the intermediate diameter dimensions of the tube rolling faces 8 adapted to roll the intermediate diameters of the outside surface 5 of the tube 4 within the diameter capacity range of the machine. The tube rolling faces 8 of the disk rollers 9 have different widths in the different sets, and the concavity thereof must be ground to suit 45 each individual diameter of the outside surface 5 of the tube 4, as later explained in connection with Figs. 16—17—18—19. Slight overlapping of the diameter capacity ranges of the sets of disk rollers 9 permits grinding the tube rolling faces 50 8 thereof without necessitating renewal of the sets for an appreciable time, and while maintaining the full diameter capacity range of the machine with these sets, as with no overlapping of the ranges any grinding would change the 55 capacity range of the set ground and thus would require renewal thereof to maintain the full range of the machine. Overlapping is accomplished by adding a small amount to the diameter of the tube rolling faces 8 of each set beyond 60 that actually required in computing these dimensions of the tube rolling faces 8 successively in ascending order as described. The forward tubular blank guide bushing 32, having outside surface 33 with shoulder 34 joining to a larger diameter rear end outside surface 35 to fit 65 removably rigidly within the central bore 36 and against shoulder 37 and counterbore 38 in the spindle housing 26 respectively, is keyed in place by means of key 39 to prevent rotation thereof and the bore 40 thereof is coaxial with the longi-

tudinal axis 23—23 of the pass 24 and has a slightly larger diameter than that of the outside surface 2 of the blank 1 to serve as a guide to the blank 1 during the tube rolling operation to prevent "whipping" of the blank 1 which would otherwise occur. The bushing 32 must be replaced by another for each size of the diameter of the outside surface 2 of the blank 1. The four spindles 14 have each an integral universal joint yoke 41 at the rear end thereof connected by 10 means of the usual universal joint cross 42 to a double universal joint yoke 43, the latter being connected to a second universal joint cross 42 connected with the universal joint yoke 44 integral with the spindle drive shaft 45. The four 15 spindle drive shafts 45 have each a spindle drive gear 46 mounted midway thereon and keyed in place by means of key 47. The four spindle drive gears 46 are laterally equally spaced peripherally in meshing engagement with the main drive gear 20 48 and are adapted to be rotatably driven by the latter. The main drive gear 48 has an integral tubular extension hub 49 extending from both sides and coaxial therewith, and to the rear thereof and integrally coaxial with hub 49 is first 25 intermediate drive gear 50, as best seen in Fig. 7. The tubular extension hub 49 is rotatably mounted, at the forward end thereof in bearing bushing 51 in central bearing 52 of the forward bearing housing 53, and at the rear end thereof in 30 bearing bushing 54 in the bearing 55 of the rear bearing pedestal 56, to rotate coaxially about the longitudinal axis 23—23 of the pass 24. The rear tubular blank guide bushing 57, having outside surface 58 with shoulder 59 joining to a 35 larger diameter rear end outside surface 60, is adapted to fit removably rigidly within the coaxial bore 61 and against shoulder 62 and in counterbore 63 in the tubular extension hub 49 respectively, being keyed in place by means of 40 key 64 to prevent rotation thereof relative to the hub 49, and held in place by retainer ring 65 attached to the rear end of the hub 49 by cap screws (not shown) to prevent endwise movement thereof, the bore 66 thereof being coaxial 45 with the longitudinal axis 23—23 of the pass 24 and slightly larger in diameter than the outside surface 2 of the blank 1, to serve as a guide for the blank 1 and prevent "whipping" of the latter which would otherwise occur during the tube 50 rolling operation. One such bushing 57 must be provided for each diameter size of the outside surface 2 of the blank 1. The four spindle drive shafts 45 are each individually rotatably mounted in bearing bushings 67 in laterally equally 55 spaced bearings 68 of the forward bearing housing 53 at the forward ends thereof, and in bearing bushings 69 in laterally equally spaced bearings 70 of the rear circular bearing ring 71 (located between the forward bearing housing 53 and the rear bearing pedestal 56) at the rear ends thereof. The rear circular bearing ring 71 has three forwardly projecting pads 72 which 60 about upon and are attached to three correspondingly rearwardly projecting brackets 73 integral 65 with forward bearing housing 53 by means of screws (not shown), so that the four spindle drive shafts 45 with the four spindle drive gears 46 mounted thereon rotate about individual axes 65 parallel to the longitudinal axis 23—23 of the 70 pass 24, as seen in Fig. 2. The first intermediate drive gear 50 meshes with and is rotatably driven by the pinion 74 integral with and rotatably driven by shaft 75 rotatably mounted in suitable bearing bushings (not shown) in the bearing 76 75

integral with rear circular bearing ring 71 and in the bearing 71 integral with the gear train double bearing pedestal 78. The shaft 75 is rotatably driven by the second intermediate drive gear 79 mounted thereon and keyed in place by means of a gib key (not shown). The second intermediate drive gear 79 meshes with and is rotatably driven by the pinion 80 integral with and rotatably driven by the shaft 81 rotatably mounted in suitable bearing bushings (not shown) in bearing 82 integral with the gear train double bearing pedestal 78 and in the bearing 83 integral with the gear train single bearing pedestal 84. The shaft 81 is rotatably driven by the flexible shaft coupling 85 keyed thereon by a gib key (not shown) to connect same to the motor shaft 86, to which the coupling 85 is also keyed by a gib key (not shown), of the electric motor 87. The electric motor 87 is controlled by the machine operator by means of the usual electric motor control switch (not shown) located at a convenient point near the machine. As best seen in Fig. 7, the longitudinally stationarily held tube bore mandrel 11 is integral with mandrel rod 88, and is held against endwise movement by the two retaining collars 89 integral with mandrel rod 88 and abutting against the forward end and rear end of the mandrel rod support bracket yoke 90 formed to receive the hexagon shank 91 between the two retaining collars 89 to hold the mandrel rod 88 and thereby the mandrel itself against rotation. The mandrel rod support bracket yoke 90 is integral with the mandrel rod support bracket 92, the latter being adapted to be moved longitudinally along a special base therefor (not shown) at the rear of the machine and to be reciprocably moved in the vertical direction by suitable power operated means (not shown) controlled by the operator to respectively suit the longitudinal position of the hexagon shank 91 on various lengths of mandrel rod 88 and to permit engagement and disengagement of the yoke 90 with the hexagon shank 91 as required, the operations being later described under the setting-up operation and operation of the machine descriptions. On the same special base for the mandrel rod support bracket 92 are mounted a series of bearing pedestals supporting a like number of semi-circular grooved rollers (not shown), the pedestals being longitudinally adjustable along the base, and the rollers vertically adjustable to suit the size of the blank 1 being rolled, to support the rear overhanging portion of the blank 1 and to facilitate entering the blank 1 into the machine, the pedestals of course being spaced to avoid interference with the bracket 92. The length of the mandrel rod 88 is such that the tubular blank 1 will clear the two retaining collars 89 and the yoke 90. The tube bore mandrel 11 is provided with a forward conical end 93 to facilitate ready entrance thereof into the bore 94 of the mandrel locating and holding sleeve 95 (seen in Fig. 10), and a rear conical end 96 to facilitate entrance thereover of the bore 3 of the tubular blank 1, as best seen in Figs. 7-9-13. The tube guide bushing 13, having bore 12 adapted to have the outside surface 5 of the helically rolled tube 4 fit tightly slidably rotatably therein and the outside surface 97 of the mandrel locating and holding sleeve 95 fit tightly slidably therein, has a circular cylindrical outside surface 98 fitting tightly within the bore 99 of the split bearing 100 provided with bearing cap 101, and is provided with a projecting annular shoulder 102 fitting within a correspond-

ing groove 103 in the bore 99 to prevent endwise movement thereof relative to bore 99, and with a longitudinal key 104 sunk in the outside surface 98 thereof fitting a corresponding keyway 105 in the bore 99 to prevent rotation thereof in the bore 99. The bearing cap 101 is held in place by means of four studs 106 with hexagon nuts 106', the studs 106 fitting within the corresponding holes in the four lugs 107 thereof and screwing into corresponding tapped holes in the lower part 10 of the bearing 100, thus by merely unscrewing the nuts 106' from studs 106 the tube guide bushing 13 may be removed when necessary to replace same with another one having a different bore 12 to suit a different outside surface 5 of 15 the tube 4, and the new tube guide bushing 13 may then be as readily clamped in place in bore 99 of the split bearing 100 with bearing cap 101. The lower part of split bearing 100 is integral with the tube guide bushing carriage 108 slidably 20 mounted on two ways 109 longitudinally parallel to the longitudinal axis 23-23 of the pass 24. The carriage 108 is provided with two longitudinal gibs 110 bolted thereto to engage the underside of the projections 111 of the two ways 25 109 integral with the carriage base 112, for holding same in place on the ways 109, as best seen in Fig. 12. A laterally adjustable gib 113 is provided to take up wear on the vertical edges of the ways 109, while leaf shims under the gibs 110 are 30 provided (not shown) to take-up wear on the horizontal surfaces of the ways 109. In the setting up of the machine, as later described, in which the position of the pass 24 is actually made to conform to the location of the bore 12 of the 35 tube guide bushing 13, and not vice versa, it will be readily understood that wear of the ways 109, or of the corresponding contacting surfaces of the carriage 108, will in no manner affect the accuracy of the location of the bore 12 of the 40 tube guide bushing 13 with respect to the pass 24, but is conditional that the carriage 108 must be held against all movement during the tube rolling operation and must maintain the setting-up position once the latter has been made. The 45 tube guide bushing carriage 108 is adapted to be locked in place against any movement on the ways 109, while at the rearward position thereof and with the tube guide bushing 13 in the operative position relative to the pass 24, by means 50 of lock pin 114 passing through the corresponding hole 115 through the same and the lug 116 alongside the inner edge of the way 109 and integral with the latter. The tube guide bushing carriage 108 is adapted to be actuated reciprocably longitudinally over the ways 109 by means 55 of pressure fluid actuated piston 117 in cylinder 118, the piston 117 having connected therewith the piston rod 119 having eye-end 120 connected to yoke lug 121 integral with the under side of the 60 carriage 108 by means of pin 122, as best seen in Fig. 7. The reciprocation of the carriage 108 is controlled by the operator by means of a valve (not shown, two-way for air, and four-way for oil or water, pressure fluid) in the pipe line from 65 a source of pressure fluid (air, oil, or water) to the pipes 123 and 124 connected to the opposite ends of the cylinder 118 mounted in the carriage base 112, the pressure fluid flow through pipe 123 causing the carriage 108 to be actuated in the 70 forward direction over ways 109 with the spent fluid leaving the cylinder 118 through pipe 124, while rearward motion of the carriage 108 over the ways 109 is caused by the flow of the pressure fluid through the pipe 124 into the cylinder 75

118 with the spent fluid leaving the cylinder 118 through pipe 123, due to corresponding manipulations of the valve by the operator. The rearward operative position of the carriage 108 on the ways 109 is accurately gauged by means of stop screw 125 screwed through the lug 126 integral with carriage base 112, the stop screw 125 abutting against lug 127 integral with the underside of the carriage 108 and is provided with lock nut 128, thus preventing the rear end of the tube guide bushing 13 from binding against the forward sides of the disk rollers 9, due to the fluid pressure in the cylinder 118 against the forward side of the piston 117, and also permits readily locking the carriage 108 on the ways 109 by means of the lock pin 114 in the holes 115, the latter being in register with the carriage 108 in the operative position. The stroke of the carriage 108 on the ways 109 in both directions is greater in 20 length than the length of the bore 12 of the tube guide bushing 13, in order to permit readily forcing the setting-up mandrel (not shown, but later fully described) into the bore 12 and in withdrawing same from the bore 12 during the setting-up operation on the machine as later explained, and in forcing the mandrel locating and holding sleeve 95 (seen in Fig. 10) into the bore 12 of the tube guide bushing 13 and over the outside surface 10 of the tube bore mandrel 11. As 30 best seen in Fig. 10, the mandrel locating and holding sleeve 95 is provided with an enlarged forward end hub 129, larger in diameter than the largest diameter of the outside surface 5 of the tube 4, adapted to fit tightly slidably within the bore 130 in the head 131 of the sleeve support bracket 132 bolted to two projecting brackets 133 integral with and one at each side of the carriage base 112, the bore 130 being coaxial with the longitudinal axis 23—23 of the pass 24. The 40 head 131 serves as an abutment for the forward end of the sleeve 95, and also for the setting-up mandrel as later described, while these are respectively forced into the bore 12 of the tube guide bushing 13 by means of the actuation of the carriage 108 over the ways 109 as described before. The rear end of the head 131 is separated from the forward end of the split bearing 100 and bearing cap 101 by a distance greater than the over-all length of the sleeve 95 and slightly less than the length of stroke of the carriage 108. The bore 130 in the head 131, being of the same diameter as the hub 129, will permit the largest size tube 4 to pass readily therethrough. A special base (not shown), similar to that at the rear 50 end of the machine, is located at the forward end of the machine, upon which are mounted a series of bearing pedestals supporting a like number of semi-circular grooved rollers (not shown), the pedestals being longitudinally adjustable along the base and the rollers vertically adjustable to suit the diameter of the outside surface 5 of the tube 4, for supporting the overhanging portion of the tube 4 beyond the forward end of the tube guide bushing 13. The carriage base 112, 60 the spindle housing 26, the forward bearing housing 53, the rear bearing pedestal 56, the gear train double bearing pedestal 78, the gear train single bearing pedestal 84, and the electric motor 87, are all rigidly bolted to the main base 134 by bolts (not shown). The main base 134 is mounted on a suitable foundation (not shown), to which it is bolted in the usual manner.

In Fig. 2 is shown one of the four disk rollers 9 having conical face 7 and tube rolling face 8 as described, and bore 135 fitting tightly removably

on the forward threaded shank 136 of one of the four spindles 14. The shank 136 is provided with key 137 sunk therein fitting the keyway 138 in roller 9, to prevent rotation of the disk roller 9 relative to shank 136. Collar nut 139, screwed onto the left hand threaded forward end 140 of the shank 136, serves to force the rear side of the disk roller 9 against the shoulder 141 formed by the juncture of the spindle 14 with the shank 136, and holds the disk roller 9 against any end-wise movement relative to shank 136. The direction of rotation of the four spindles 14 and the four disk rollers 9 in this instance being right hand, or so-called clockwise, the collar nut 139 must screw onto the threaded end 140 in the reverse direction or left hand in order that the rotation of the assembly cannot cause unscrewing of same from the threaded end 140. The rotation of the tubular blank 1 and tube 4, of course, will be the reverse of that of the disk rollers 9, 20 since the latter rotatably drive the blank 1 about the longitudinal axis 23—23 of the pass 24, as seen in Fig. 5. The double universal joints, connecting each of the four spindles 14 with the four spindle drive shafts 45, already partially described 25 in connection with Fig. 1, are of the usual oversize bushing four trunnion cross type, shown here turned through 90 degrees from the proper one to correspond to the view in Fig. 1 in order to clearly show the construction. Lubrication 30 consists of cup grease contained in raw hide shoes (not shown) attached in the usual manner to completely surround each of the eight crosses 42. It should be noted that the four spindle drive gears 46 and universal joint yokes 44 are free to 35 move endwise slightly to permit unrestricted rotation of the four eccentric sleeves 18 when the latter are adjusted. A thrust washer 142 is loosely mounted on each of the four spindles 14 between the rear sides of the disk rollers 9 and 40 the forward ends of the four eccentric sleeves 18, to prevent friction and wear of the sleeves 18. Each of the four spindles 14 is adapted to be lubricated by lubricant flowing from the reservoir 45 formed by the space between the ends of the two bushings 15 and 16 in the eccentrically located bores 17 into suitable grooves (not shown) cut in the bores in bushings 15 and 16, the reservoir in each instance being connected by means of drilled holes through the walls of the sleeves 18 50 to an annular groove in each bore 25 in spindle housing 26 connected to a drilled and tapped hole to which is attached suitable piping connected to a suitable source of pressure lubricant. The bearing bushings for other shafts of the 55 machine are supplied with similar means (not shown) for pressure lubrication. Each of the four disk rollers 9 has a conical face 7 rearwardly adjacently coaxial with the tube rolling face 8 to facilitate entrance of the material of the walls 60 of the tubular blank 1 between the tube rolling faces 8 and the outside surface 10 of the tube bore mandrel 11 within the pass 24, and also to prevent the formation of a vertical shoulder in the unrolled portion of the outside surface 2 of the 65 blank 1 by the rear edge of the tube rolling face 8, which would occur in the absence of the conical face 7, and which would cause the tube rolling face 8 of the disk roller 9 adjacent to the one in question to compressively roll this vertical 70 shoulder of material in the rearward and forward longitudinal directions as well as radially. The forward longitudinal compression spread of the material is undesired as it would cause formation of a forwardly projecting helical fin of com- 75

pressed material overlying and only partially rolled into the surface 5 of the tube 4 produced by the disk roller 9 in question, and this fin in most cases would flake out or leave a helical mark on the surface 5 of the tube 4. Both the forward and the rear edges of the tube rolling face 8 in each instance are slightly rounded to prevent any scoring of the outside surface 5 of the tube 4 thereby. The four disk rollers 9 are each provided with a heavy boss 143 at the forward side thereof in order to increase the length of the bore 135 and the keyway 138 and consequently increase the area in contact with the shank 136 and the key 137 to prevent upsetting of the metal of the contacting surfaces under the heavy loads to which they are subjected, as well as to increase the strength of the disk roller 9 itself in resisting the very heavy combined radial thrust and rearward longitudinal thrust thereon during the tube rolling operation. Each of the four eccentric sleeves 18 is securely clamped in place, after the individual manual adjustments of the tube rolling faces 8 of the disk rollers 9 have been made as described, individually in the four bores 25 in the spindle housing 26 by means of two set screws 144 in each case screwed through the walls of the bores 25 (the screws 144 shown dotted, the wall of bore 25 being cut away in this view) and abutting against the outside surface 20 of the sleeve 18. The four eccentric sleeves 18 are each held against endwise movement in their individual bores 25 in the spindle housing 26 in each instance by means of the forward and rear sides of the worm gears 19 integral therewith and contained in the counterbore recess 145 in the split combined worm and worm gear housing 146 attached in each case by means of screws 147 to the four rear bosses 148 at the rear ends of the bores 25. The worm 21 is seen in mesh with the worm gear 19, the plain worm shaft 22' being dotted, while the square end worm shaft 22 being in the right half of the housing 146 does not appear in this view, as only the left half of housing 146 is shown. To facilitate illustration the parts in this view are shown coaxial, though the true relation therebetween is non-coaxial as seen in Fig. 1. The longitudinal axis 28-28 of the outside surface 20 of the eccentric sleeve 18 (coinciding with the axis 27-27 of the bore 25 in spindle housing 26 in each instance) is seen to be parallel to the longitudinal axis 30-30 of the spindle 14 and disk roller 9 (coinciding with the axis of the eccentrically located bore 17 in sleeve 18) separated by the distance equal to the eccentricity 31.

In Fig. 3 is shown the split combined worm and worm gear housing 146 having the counterbore recess 145 containing the worm gear 19 meshing with the worm 21, with the square end worm shaft 22 and plain worm shaft 22' coaxially projecting from each end of worm 21 rotatably mounted in bearings 150 and 149 respectively in the right and left halves of housing 146, attached by screws 147 to the boss 148 (seen in Fig. 2). Two collars 151 are screwed onto shafts 22 and 22' to prevent endwise movement of the latter in bearings 150 and 149. The set screws 152 are employed to prevent inadvertent turning of shafts 22 and 22', after adjustments of the tube rolling faces 8 of the disk rollers 9 have been made as described.

In Fig. 4 is shown one of the four eccentric sleeves 18 rotatably mounted in one of the four bores 25 in the spindle housing 26 to rotate about the longitudinal axis 28-28, and one of the four

spindles 14 rotatably mounted in the forward bearing bushing 15 (the rear bearing bushing 16 being in the part cut away in this view), pressed in place in the eccentrically located bore 17 of the eccentric sleeve 18, to rotate about longitudinal axis 30-30. The longitudinal axes 28-28 and 30-30 are parallel to each other and separated by the distance equal to eccentricity 31, so that the rotation of the sleeve 18 about axis 28-28 causes the axis 30-30 to describe a circular cylindrical surface having a radius equal to eccentricity 31 when the full adjustment of the tube rolling faces 8 of the disk rollers 9 is made with relation to the longitudinal axis 23-23 of the pass 24, the full radial adjustment of the latter then being twice the eccentricity 31 or the diameter of the small circle of radius 31 seen here. A fragment of the forward tubular blank guide bushing 32 (seen slightly in perspective here) is shown within the bore 36 in the spindle 20 housing 26, the bore 40 being coaxial with the longitudinal axis 23-23 of the pass 24.

In Fig. 5 is shown the forward end of the spindle housing 26, and the four disk rollers 9; the four spindles 14 are dotted in to show their longitudinal axes 30-30 parallel in each instance to the longitudinal axes 28-28 of the four eccentric sleeves 18 (the latter not being shown), and the two axes 30-30 and 28-28 in each instance are angular to the longitudinal axis 23-23 of the pass 24. The pass 24 in this view coincides with the outside surface 5 of the tube 4 within the bore 12 of the tube guide bushing 13. The outside surface 98 of the tube guide bushing 13 is within the bore 99 of the split bearing 100 and bearing cap 101 as seen, only the projections 153 between the four disk rollers 9 of the bearing 100 and cap 101 being seen here in full line, while the projections 154 of the tube guide bushing 13 are shown dotted between the four disk rollers 9. The projections 153 and 154 are seen also in Figs. 20-21. The direction of rotation of the disk rollers 9 and spindles 14 is indicated by the curved arrows and is seen to be clockwise (right hand), while that of the tube 4 also indicated by a curved arrow is seen to be counter-clockwise (left hand). The bottom surface 155 of the spindle housing 26 is machined to adapt same to fit corresponding finish pads on the top surface of the main base 134. The bolt holes 156 (dotted) are provided to receive bolts (not shown) for attaching the spindle housing 26 to the main base 134 on the finish pads mentioned. The mandrel rod 88 is shown dotted to the rear of the tube bore mandrel 11 within the bore 3 of the blank 1, and is coaxial with the bore 6 of the tube 4 and to longitudinal axis 23-23 of the pass 24. It will be readily apparent that the mandrel rod 88 may be employed forward of the tube bore mandrel 11 when desired, instead of to the rear of the latter as here shown, without affecting the operation of the tube bore mandrel 11, though causing the mandrel rod 88 to be thrust loaded instead of tension loaded as in the application herein shown, which would not be desirable in the case of long or small diameter mandrel rods 88 due to excessive sagging and buckling of the same under load. The mandrel locating and holding sleeve 205, employed with the movable type tube bore mandrel 202, seen in Figs. 25-26-27 and later described, would have to be employed in place of the sleeve 95 in the event that the mandrel rod 88 is applied forward of the tube bore mandrel 11, in order to avoid interference with the bore 130 in the head 131 of the sleeve support bracket 75

132 by the hub 129 and eye-lever 157 of the sleeve 95 which would occur otherwise. By mounting the sleeve support bracket 132 on a horizontal axis pivot, to permit swinging same upward out 5 of the way when not in use, the difficulty with the sleeve 95 as outlined may be avoided.

In Fig. 6 the rear end of the spindle housing 26 is shown, the direction of rotation of the parts being seen to be opposite to that shown in Fig. 5 10 for obvious reasons, and the location of the square end worm shafts 22 is seen to be best suited to permit ready access thereto by the operator.

In Figs. 7-8 the parts shown have been fully described in connection with Figs. 1-2.

15 In Figs. 9-10-11-12-13-14-15 are shown the detail parts associated with the application of the mandrel locating and holding sleeve 95 to the bore 12 of the tube guide bushing 13 and to the outside surface 10 of the forward end extension 20 of the tube bore mandrel 11, while the forward end portion of the tubular blank 1 is progressively helically rolled within the pass 24 to progressively form the forward end portion of the tube 4 (equal in length to the length of the bore 12 of the tube 25 guide bushing 13), for the purpose of locating and holding the tube bore mandrel 11 longitudinally coaxially within the pass 24 during this period. The start of the tube rolling operation 25 on the tubular blank 1 is seen in Fig. 9, with the forward end of the tubular blank 1 just contacting with the rear end of the mandrel locating and holding sleeve 95. As the tube rolling operation proceeds, the mandrel locating and holding sleeve 95 is progressively displaced from 30 within the bore 12 of the tube guide bushing 13 and from over the outside surface 10 of the forward end extension of the tube bore mandrel 11 within the bore 12 of the tube guide bushing 13 by the progressively formed forward end portion 35 of the tube 4, as seen in Fig. 13, the tube 4 thus progressively assuming the same function as the mandrel locating and holding sleeve 95 in locating and holding the tube bore mandrel 11 longitudinally coaxially within the pass 24, and 40 serving jointly with the mandrel locating and holding sleeve 95 in this capacity in cooperation with the bore 12 of the tube guide bushing 13 and the outside surface 10 of the forward end extension of the tube bore mandrel 11 within the 45 period. After the mandrel locating and holding sleeve 95 has been entirely displaced from within the bore 12 of the tube guide bushing 13 and from over the outside surface 10 of the forward end extension of the tube bore mandrel 11 within the 50 bore 12 of the tube guide bushing 13, the tube 4 in cooperation with the bore 12 of the tube guide bushing 13 and the outside surface 10 of the forward end extension of the tube bore mandrel 11 serves to locate and hold the tube bore 55 mandrel 11 longitudinally coaxially within the pass 24 while the remaining portion of the tubular blank 1 is progressively helically rolled within the pass 24 to progressively form the remaining portion 60 of the tube 4. Thus, since the tube bore mandrel 11 has been located and held longitudinally coaxially within the pass 24 throughout the tube rolling operation on the tubular blank 1, the outside surface 5 and the bore 6 of the tube 4 are formed perfectly longitudinally coaxial to 65 each other for the full length thereof. The tube rolling operation on the tubular blank 1, after the mandrel locating and holding sleeve 95 has been entirely displaced by the tube 4 as described, is seen in Fig. 7. During the entire course of the 70 tube rolling operation on the tubular blank 1, the bore 12 of the tube guide bushing 13, besides serving in the capacity mentioned above, serves to guide the outside surface 5 of the tube 4 longitudinally coaxially forwardly adjacently in alignment with the tube rolling faces 8 of the four disk rollers 9 tangent to the pass 24, so that the outside surface 5 of the tube 4 is perfectly straight longitudinally for its full length. The outside surface 10 of the forward end extension 75 of the tube bore mandrel 11 within the bore 12 of the tube guide bushing 13, besides serving in the capacity mentioned above, serves to guide the bore 6 of the tube 4 longitudinally coaxially forwardly adjacently in alignment with the outside surface 10 of the tube bore mandrel 11 within the 80 pass 24 during the entire course of the tube rolling operation on the tubular blank 1 (in co-operation with bore 12 of the tube guide bushing 13 and the sleeve 95 and the tube 4), so that the bore 6 of the tube 4 is perfectly straight longitudinally for its full length, as seen in Figs. 7-9-13. The foregoing functions apply to all modifications of the two types of tube bore mandrels, for all lateral sectional forms of the bore 6 of the tube 4. Where the bore 6 is of non-circular 85 lateral sectional form, an additional function arises, and the stationarily held tube bore mandrel 11 must be modified to suit, as described in connection with Figs. 16-23-24, to comprise a rotatably mounted cylindrical sleeve on a stationary held shank suitably connected to the mandrel rod 88. The outside cylindrical surface of the sleeve, having the same lateral sectional form and dimensions as the required bore 6 of the tube 4, in the case of the stationarily held 90 tube bore mandrel 11, is operable in the same manner as the cylindrical or non-cylindrical outside surface 203 of the longitudinally movable type tube bore mandrel 202, described in connection with Figs. 25-26-27, in that the forward end extension thereof, in both cases within the bore 12 of the tube guide bushing 13, serves to hold the forming surfaces thereof within the pass 24 against any rotary movement relative to the bore 6 of the tube 4 while guiding the bore 6 in alignment with the forming surfaces thereof 95 throughout the tube rolling operation on blank 1. Thus, where the bore 6 is hexagonal in lateral sectional form, for example, each apex of the hexagon will be longitudinally straight throughout the length of the bore 6. Other characteristics of the tube 4, among the six mentioned, follow largely from the two outlined above. The concentricity of the outside surface 5 and bore 6 of the tube 4, and of the bore 12 of the tube 100 guide bushing 13, and of the outside surface 10 of the forward end extension of the tube bore mandrel 11, about the longitudinal axis 23-23 of the pass 24, is seen in Fig. 15, to show the uniform wall thickness of the tube 4, as contrasted 105 with the non-uniform wall thickness of the blank 1 and the non-concentric relation of the latter to the bore 40 of the forward tubular blank guide bushing 32 and the mandrel rod 88, seen in Fig. 14, which also shows the necessary clearance required for the blank 1 in bore 40. In Figs. 10-11 110 is seen the mandrel locating and holding sleeve 95, having outside surface 97 and bore 98 respectively of the same lateral form and dimensions as outside surface 5 and bore 6 of tube 4, 115 and provided with an enlarged forward end hub 129 (already described) to fit within bore 130 in the head 131 of sleeve support bracket 132 and an eye-lever 157 for facilitating handling same by means of a crane chain and hook, the two 120

diametrically oppositely projecting lugs 158 integral therewith are adapted to fit tightly within the annular groove 159 within the bore 99 of the split bearing 100 and bearing cap 101 formed between the forward end of the tube guide bushing 13 and the inwardly projecting annular end shoulder 160 of the bearing 100 and cap 101 seen in Fig. 13, the two lugs 158 being permitted to enter the groove 159 through the two radial slotted openings 161 and 162 forward of the groove 159 at the forward end of the bearing 100 and cap 101. A pin 163 serves as a stop for the eye-lever 157 to insure proper register of the two lugs 158 with the slotted openings 161 and 162 when the carriage 108 forces the mandrel locating and holding sleeve 95 into the bore 12 of the tube guide bushing 13 as seen in Figs. 9-12. When the assembly of the mandrel locating and holding sleeve 95 within the bore 12 of the tube guide bushing 13 is forced over the outside surface 10 of the forward extension of the tube bore mandrel 11 by means of carriage 108, the eye-lever 157 is turned through 90 degrees as seen in the dotted position in Fig. 12 to lock the lugs 158 within the groove 159 and thus prevent relative movement of the mandrel locating and holding sleeve 95 within the bore 12 of the tube guide bushing 13. After the mandrel locating and holding sleeve 95 has been thus completely assembled within the bore 12 of the tube guide bushing 13 and over the outside surface 10 of the forward extension of the tube bore mandrel 11 within the bore 12 of the tube guide bushing 13, the eye-lever 157 is again returned to the vertical position as seen in Figs. 9-12 in order to register the two lugs 158 with the slotted openings 161 and 162 and permit the mandrel locating and holding sleeve 95 to be displaced from within bore 12 and from over the surface 10 as seen in Fig. 13 during the tube rolling operation. While the above description applies to the longitudinally stationarily held type of tube bore mandrel as seen in Figs. 1-5-6-7-9-12-13-15-23-24, the longitudinally movable type of tube bore mandrel 202 as seen in Figs. 25-26-27 is applied in a very similar manner in connection with the mandrel locating and holding sleeve 205 there shown, as later fully explained.

In Fig. 16 is shown a portion of the tubular blank 1 and a portion of the helically rolled tube 4 made therefrom, the outside surface 2 and the bore 3 of the blank 1 being non-coaxial the walls are necessarily non-uniform in thickness, while the outside surface 5 and the bore 6 of the tube 4 are concentric about the longitudinal axis 23-23 of the pass 24 and thus the walls are uniform in thickness. The pass 24 lies between the two lateral lines 164 and 165, the tubular blank 1 lying to the rear of line 164 and the tube 4 lying forward of the line 165. One of the four disk rollers 9 is shown dotted, having its longitudinal axis 30-30 at angle 29 to the longitudinal axis 23-23 of the pass 24. This view shows the true relation existing between the longitudinal axes 30-30 of all four disk rollers 9 and the longitudinal axis 23-23 of the pass 24 as seen when viewed from each of the four positions 166, 167, 168, 169, indicated by the arrows in Fig. 5, as well as the relation of the tube rolling faces 8 of all four disk rollers 9 to the pass 24. Each of the tube rolling faces 8 of the four disk rollers 9 contacts with the outside surface 2 of the blank 1 in a small contact area bounded by two approximately lateral edges 170' and 171' produced by the rear edge 170 and forward edge 171 of the tube rolling face 8 and by the two edges

172 and 173 parallel to the axis 30-30 produced by the tube rolling face 8 when entering and when leaving the contact area respectively. The leaving edge 173 will lie directly under the line of the longitudinal axis 30-30 in the figure and between the bounding lateral lines 164 and 165 of the pass 24, and is the momentary limit of the helical path 174 of this particular disk roller 9, the helical paths of the three remaining disk rollers 9 being 175, 176, 177, as seen in the drawings. As seen, the surface of the tube rolling face 8 contacting as it does with a circular cylindrical helical path 174 in the leaving edge 173 lying in path 174, and the leaving edge 173 thus being common to both the tube rolling face 8 and the path 174, the surface of the tube rolling face 8 must be made concave to suit the exact diameter of the path 174. The slight addition to the contact area of the tube rolling face 8 produced by the conical face 7 is located to the rear of the rear edge 170 of the tube rolling face 8, and is therefore to the rear of the pass 24 and the bounding line 164 of the latter, is not shown as it is not of consequence to the description. From the description of the eccentric sleeves 18, 25 it will be clear that the adjustments made thereby will not alter the angle 29 between the longitudinal axis 30-30 of each of the disk rollers 9 and the longitudinal axis 23-23 of the pass 24, due to the parallelism of the axes of the sleeves 18, 20 The helical path 174 of the tube rolling face 8 of the disk roller 9 shown, is cross hatched to clearly distinguish same from the other three 175, 176, 177, and all four paths are produced simultaneously as the four disk rollers 9 are 35 rotatably driven by the four spindles 14, etc., as described. The angle 29 between the axes of the disk rollers 9 and the pass 24 causes the disk rollers 9 not only to rotatably drive the blank 1 to rotate about the longitudinal axis 23-23 of 40 the pass 24 but to feed the blank 1 progressively longitudinally forward, so that the material of the walls of the blank is helically rolled between the tube rolling faces 8 of the disk rollers 9 and the circular cylindrical outside surface 10 of the tube bore mandrel 11. Where the outside surface 10 of the tube bore mandrel 11 must be non-circular cylindrical, such as hexagonal, etc., the mandrel 11 must be rotatably mounted on a shank (held against rotation by the mandrel rod 50 88) or else the longitudinally movable type of tube bore mandrel must be employed which rotates with and moves longitudinally forward with the blank 1 and tube 4 as later explained, the mandrel locating and holding sleeve 95 having a bore 94 55 to suit the form of the surface 10 of the tube bore mandrel 11 in this case as well as with the movable type of mandrel. Collectively, the four helical paths 174, 175, 176, 177, as they are progressively produced by the four tube rolling faces 8 60 within the pass 24, progressively form the circular cylindrical outside surface 5 of the tube 4. The circular cylindrical bore 6 of the tube 4 is simultaneously progressively formed within the pass 24 by the outside surface 10 of the tube bore 65 mandrel 11 as the outside surface 5 of the tube 4 is helically rolled, as seen in Fig. 7. The angle 29 between the longitudinal axes 30-30 of the four disk rollers 9 and the longitudinal axis 23-23 of the pass 24 is likewise equal to the helix angle 70 of each of the four helical paths 174, 175, 176, 177, the latter having each a linear pitch 178 (or lead) in this instance made equal to the diameter of the outside surface 5 of the tube 4. Thus, with the angle 29 constant, the linear pitch 178 75

will vary in direct proportion to the diameter dimension of the outside surface 5 of the tube 4 being rolled, for all diameters within the diameter capacity range of the machine. The width 179 of the tube rolling face 8 of the disk rollers 9, based on the angle 29 and the linear pitch 178 as given, is equal to one-fourth of the pitch 178, or one-fourth of the diameter of the outside surface 5 of the tube 4, and will also vary in direct proportion to the diameter dimension of the outside surface 5 of the tube 4 being rolled. Thus, for a 4" O. D. tube, the linear pitch 178 will be equal to 4" and the width 179 will be equal to 1"; while for a 2" O. D. tube, the linear pitch 178 will be equal to 2" and the width 179 will be equal to $\frac{1}{2}$ ". In any given machine, once the angle 29 has been determined, it cannot, of course, be altered in any manner, and therefore the machine must be designed to suit the hardest material which it will be called upon to roll; the harder the material the smaller the width 179 of the tube rolling faces 8 of the disk rollers 9, and, consequently, the smaller the angle 29 and the linear pitch 178 to conform to the width 179. By employing the width 179 as herein designated, a slight overlap 180 of the helical paths 174, 175, 176, 177, is provided, thus, the path 174 overlaps path 175, the path 175 overlaps path 176, the path 176 overlaps path 177, the path 177 overlaps the path 174, as seen in the drawings. With the data for each set of disk rollers 9 determined in this manner, the plurality or series of sets of disk rollers 9 to suit the diameter capacity range of the machine is readily computed. While the machine herein described is provided with four disk rollers 9, the number of rollers is governed by the smallest diameter tube to be rolled and the diameter capacity range of the machine, as is likewise the number of sets of rollers. The number of disk rollers 9 employed in any size machine should never be less than three, and the larger the number of disk rollers 9 the better. This may be seen from the fact that, with the same angle 29, if the number of disk rollers 9 were increased from four to five, the width 179 would be diminished and would be only one-fifth of the linear pitch 178 in place of one-fourth, and would thus serve to diminish the contact area 170'-171'-172'-173' of the tube rolling faces 8 by making same narrower, thereby decreasing the loading on the disk rollers 9 and the spindles 14 and other connected driving parts. The increased number of disk rollers 9 also serves to distribute the radial loading on each of the tube rolling faces 8 at smaller angular intervals about the circumference of the outside surface 2 of the blank 1 within the pass 24, which is very important in reducing the amount of the unbalanced radial loading on the tube rolling faces 8 at points in the outside surface 2 of the blank 1 at which the material being rolled is thicker than at diametrically opposite points, which latter condition would tend to cause the tube 4 with the tube bore mandrel 11 within the bore 6 of tube 4 to be deflected within the pass 24 toward the points of less radial loading and thereby deflect the tube bore mandrel 11 from the desired coaxial relation to the pass 24 and cause the tube 4 to be imperfectly rolled if adequate counter means were not provided to prevent such deflection. The moment arm of the radial loading on each of the tube rolling faces 8 is approximately one-half of the width 179 with respect to the rear end of the bore 12 of the tube guide bushing 13, and thus the decrease in width 179 and the corresponding

decrease in the radial loading, with better distribution at small angular intervals with greater numbers of disk rollers 9, is readily apparent, and by making the length of the bore 12 of the tube guide bushing 13 very many times greater than the width 179 within practicable limits, the resistance to deflection of the tube 4 and the tube bore mandrel 11 within the bore 12 of the tube guide bushing 13 will be ample to prevent the deflection of the tube 4 and tube bore mandrel 11 within the pass 24. It is for these reasons that I consider the disk rollers 9 superior to any other form of tube forming means, and the machine herein described the preferred embodiment of my invention. The effect of the long 15 mandrel rod 88, unsupported between the rear conical end 96 of the tube bore mandrel 11 and the yoke 90 of the mandrel rod support bracket 92, and, therefore, subject to considerable deflection due to its weight, is to tend to deflect the 20 tube bore mandrel 11 from the required coaxial relation to the longitudinal axis 23—23 of the pass 24 during the tube rolling operation. To prevent such action as much as possible, due to the above cause, or due to inadvertent misalignment of 25 the mandrel rod 88 and the tube bore mandrel 11, a universal joint such as the universal joint 279' seen in Fig. 30, must be connected to the forward end of the mandrel rod 88 and the rear end of the rear conical end 96 of the tube bore 30 mandrel 11, one yoke of the universal joint being integral with the mandrel rod 88 while the other yoke is integral with the rear conical end 96 of the tube bore mandrel 11, a four trunnion cross piece connecting the two yokes in the usual manner. The width 181 of the conical faces 7 of the four disk rollers 9 will vary in proportion to the width 179 of the tube rolling faces 8, and must be sufficiently wide to permit the material of the outside surface 2 of the blank 1 to contact therewith only within this width and not with the rear edge of the conical face 7. The angle 182 of the conical faces 7 must conform to the same condition as pertain to the width 181 thereof, and also must serve to prevent the longitudinally forward compression spread of the material of the outside surface 2 of the blank 1, as already described. The widths 179 and 181 of the four disk rollers 9 are made suitable for helically rolling tubes 4 within the diameter capacity range of each set, the widths being the same for each set, but vary between the different sets comprising the series of sets required for the machine. In Figs. 17-18-19, are shown the requirements 55 for grinding the tube rolling faces 8 of the four disk rollers 9 to the required concavity, as explained in connection with the description of Fig. 16. The disk roller 9 is to be mounted on a suitable mandrel in a grinding machine, in which the tube rolling face 8 contacts with the face of the grinding wheel 183 of the same diameter as the outside surface 5 of the tube 4. The axis 184 of the disk roller 9 being at angle 185 to the longitudinal axis 186 of the grinding wheel 60 183, respectively corresponding to the longitudinal axis 30—30 of the four disk rollers 9 at the angle 29 to the longitudinal axis 23—23 of the pass 24 and the outside surface 5 of the tube 4 in the tube rolling machine, the required concave surface 65 of the tube rolling face 8 of the disk roller 9 is accurately ground. The disk roller 9 and the grinding wheel 183 are independently rotatably driven in the grinding machine to rotate about their respective axes 184 and 186 in the same 70 75

directions of rotation, as seen in Fig. 18. The diameter of the tube rolling faces 8 of the four disk rollers 9 comprising each set must be exactly equal. The conical faces 7 of the four disk rollers 9, are to be ground in the usual manner in a grinding machine, the angle 182 and the width 181 and the diameter being the same in each set.

In Figs. 20-21-22, is shown the tube guide bushing 13 mounted in the bore 88 of the split bearing 100 and bearing cap 101, as already described, other detail parts being numbered the same. In order to provide for lubrication of the bore 12 of the tube guide bushing 13, two annular grooves 187 and 188 are cut near each end in the bore 12 and connected by means of helical groove 189 cut therein, small drilled holes 190 at intervals connect the helical groove 189 with an annular recess 191 in the bore 88 of the split bearing 100 and bearing cap 101, the drilled and tapped hole 192 being provided in the bearing cap 101 for making connection to suitable flexible piping (not shown) to connect the recess 191 to other common piping (not shown) connected to a source of lubricant under pressure (not shown). For helically rolling the tubular blank 1 in a heated state (at the so-called rolling heat), water under pressure must be substituted for oil or other lubricant, in order to prevent distortion of the bore 12 of the tube guide bushing 13 and severe abrasion therein which would otherwise occur, due to the heat in the tube 4 passing therethrough. It is also desirable to direct a stream of oil for cold worked tubes, and water for hot worked tubes, against the outside surface 5 of the tube 4 within the tube rolling space 24, by means of suitably disposed pipes, in order to further secure proper lubrication and cooling. To reduce the friction of the outside surface 5 of the tube 4 within the bore 12 of the tube guide bushing 13 still further, a rotatably mounted sleeve (not shown), having the same diameter bore as the bore 12, may readily be placed within a suitable counterbore within the bore 12 between the two annular grooves 187 and 188 (the latter grooves being dispensed with in that event) and held against endwise movement by means of a short locking bushing screwed into the counterbore at the forward end up to the point of the groove 188, the bushing also having a bore of the same diameter as the bore 12. Other alternatives to the rotatably mounted sleeve above mentioned consist of: A series of roller bearings, the inner diameter of the bearings being equal to that of the bore 12 to permit the rollers of the roller bearings to contact rotatably with the outside surface 5 of the tube 4; or of a series of roller bearings having inner rings with bores of the same diameter as the bore 12 to permit the bores of the inner rings to contact with the outside surface 5 of the tube 4 and the rollers themselves rollably contacting with the surface of the counterbore above mentioned; or a series of plain rings having bores of the same diameter as the bore 12 rotatably mounted in the counterbore above mentioned; all these alternative constructions being particularly suitable for cold worked tubes. The conical entrance bore 193 at the rear end of the bore 12 of the tube guide bushing 13 is provided to facilitate the entrance of the forward end of the outside surface 5 of the tube 4 therein, and extends rearward as shown within the projections 154 between the four disk rollers 9 formed by the four clearance notches 194 provided to clear the forward sides of the four disk rollers 9. The four projections 153 are formed by the four clearance notches 195 provided in the

rear end of the split bearing 100 and bearing cap 101 to clear the forward sides of the four collar nuts 139 on shanks 138 of the four spindles 14. The projections 153 and 154 are shaded in Fig. 20 to more clearly show the relation therebetween. The dotted fragment of one of the disk rollers 9 shows the longitudinal relation between the same and the conical entrance bore 193 and the notches 194 and 195 (Fig. 22 clearly shows the entrance bore 193) though not in true radial position with the tube rolling face 8 in longitudinal alignment with the bore 12 of the tube guide bushing 13.

In Figs. 23-24, is shown the tube bore mandrel 11 provided with mandrel rod 88, and the rear conical end 96, and the forward conical end 93, and the circular cylindrical outside surface 10, as already described. In order to provide for lubrication of the outside surface 10, two annular grooves 186 and 187 are cut in the surface 10 at each end, corresponding in location to the grooves 187 and 188 cut within the bore 12 of the tube guide bushing 13 as seen in Fig. 21, and connected by means of helical groove 189 cut therein, small drilled holes 190 at intervals connect the helical groove 189 with the centrally located longitudinally drilled hole 200 in the body of the tube bore mandrel 11, the longitudinal hole 200 being connected to the bore 201 in the mandrel rod 88, the latter in this case being a tube of proper dimensions welded to the rear conical end 96, the bore 201 being provided at the extreme rear end with a tapped hole (not shown) for making connection to suitable flexible piping (not shown) to connect the same to a source of lubricant under pressure (not shown). When the universal joint 35 connection (not shown, described in connection with the description of Fig. 16) between the rear conical end 96 and the forward end of the mandrel rod 88 is employed, a flexible pipe passing through the trunnion part of the universal joint 40 must be used to connect the longitudinal hole 200 in the mandrel 11 with the bore 201 of the tubular mandrel rod 88, in order to lubricate in the same manner as with the rigid connected tube bore mandrel 11 and mandrel rod 88 as above outlined. For helically rolling the tubular blank 1 while heated (at the so-called rolling heat), water under pressure must be substituted for oil or other lubricant, in order to prevent distortion of the outside surface 10 and severe abrasion thereof which would otherwise occur, due to the heat in both the blank 1 and the tube 4 passing thereover. In order to further reduce the friction between the bore 6 of the tube 4 and the outside surface 10 of the tube bore mandrel 11, a rotatably mounted sleeve as described before in connection with Fig. 16, but of modified form, having the same outside surface diameter as the outside surface 10, may readily be placed upon a suitable shank integral with the rear portion of the mandrel 11 and occupying the space between the two grooves 199 and 197 (the latter grooves being dispensed with in that event) and held against endwise movement on the shank by means of a locking nut screwed onto the shank at the forward end of the latter up to the forward end of the rotatably mounted sleeve and held by means of a pin against unscrewing, the locking nut also having a circular cylindrical portion of the same diameter as the outside surface 10 adjacent to the sleeve, and a forward end portion tapered to form a conical end the same as the forward conical end 93. The lubrication of the rotatably mounted sleeve being provided for the same as for the solid mandrel 11, by means of a

longitudinal bore in the shank with drilled holes serving the interior of the bore of the sleeve, and thence through drilled holes in the walls of the sleeve to a helical groove on the outside surface 5 of the sleeve. Other alternative constructions to the one with the rotatably mounted sleeve mentioned above, consist of: A series of roller bearings mounted on the shank in place of the sleeve, the outside diameter of the bearings being the same as the sleeve diameter to permit the rollers to contact rollably with the shank and with the bore 6 of the tube 4; or of a series of roller bearings, having outer rings with the same outside diameter as the sleeve, mounted on the shank in place of the sleeve, the outside surface of the rings contacting with the bore 6 of the tube 4 and the rollers with the shank; or a series of plain rings, mounted on the shank in place of the sleeve, having the same outside surface diameter as the sleeve and bore of the same diameter as the shank, the outside surface contacting with the bore 6 of the tube 4 and the bore rotatable on the shank. The lubrication of these roller bearings and plain rings being provided for the same as for the sleeve. The sleeve and the roller bearings and plain rings being suitable for cold worked tubes chiefly. Where the bore 6 of the tube 4 is of non-circular cylindrical form, the rotatably mounted sleeve, as described before in connection with Fig. 16, having the outside surface conforming to the requirements of the bore 6 and of the same cross sectional form and dimensions, is mounted on a stationarily held shank integral with the rear conical end 96 and extending for the full length equal to the length of the outside surface 10 of the tube bore mandrel 11, the locking nut on the forward end of the shank in this case having merely the form of the forward conical end 93. The rotatably mounted sleeve thus rotating freely about the longitudinal axis 23-23 of the pass 24 on the shank held stationary by the mandrel rod 88. The large end of the two conical ends 96 and 93, in this case, must be smaller in diameter than the smallest lateral dimension of the outside surface of the rotatably mounted sleeve in order to avoid interference with the non-circular cylindrical bore 6 of the tube 4. The mandrel locating and holding sleeve 95 must be modified to resemble the sleeve 205, seen in Fig. 25, without the eye-lever 151 and other projecting parts which would prevent rotation thereof with the rotatably mounted sleeve mentioned above, and must also have a bore 94 of the same lateral sectional form and dimensions as the outside surface of the rotatably mounted sleeve.

In Figs. 25-26-27, is shown the longitudinally movable tube bore mandrel 202, having an hexagonal cylindrical surface 203, greater in length than the tube 4 made thereover, the blank 1 being shown loosely fitting thereon. The shank 204, of circular cylindrical form, is coaxially integral with mandrel 202 at the forward end of the latter, and has the mandrel locating and holding sleeve 205 removably tightly slidably mounted thereon. The sleeve 205 has a circular cylindrical outside surface 206 of the same diameter as the outside surface 5 of the tube 4; each pass of the tube 4 through the machine, of course, requiring a different sleeve 205 having a different suitable diameter of the outside surface 206, the successive passes of the tube 4 requiring the diameter of the outside surface 206 to be correspondingly successively smaller. For each pass of the tube 4 through the machine, the machine must be reset

as described, including a different tube guide bushing 13 with a smaller diameter bore 12. By grinding the tube rolling faces 8 of the disk rollers 9 to suit the smallest (or finished) diameter of the outside surface 5 of the tube 4, no grinding of the faces 8 will be required for the passes prior to the last (or finishing) pass. In practical commercial work there will be a large number of mandrels 202, in fact equal to the number of tubes 4 in most cases, and the number of the setting-up operations will be greatly reduced by rolling large lots of tubes 4 for each setting of the machine. The length of shank 204, and of the mandrel locating and holding sleeve 205, is equal to the length of the bore 12 of the tube 16 guide bushing 13. The outside surface 203 of the mandrel 202 may be of any desired cross sectional form, as circular or non-circular, and may be cylindrical or non-cylindrical. The tube 4 is not removed from the mandrel 202 until after the last pass or finishing pass, and is then removed in a stripping machine in the same manner as in the past. To facilitate ready removal of the tube 4 where the bore 6 is of unusual form, and not otherwise removable in the usual manner by withdrawing longitudinally the mandrel 202 from the bore 6 of the tube 4, the mandrel 202 may be made longitudinally sectional of a number of segmental longitudinal pieces mounted to be securely held in place on a central longitudinal shank 30 integral with the shank 204 and extending coaxially rearwardly from the latter, so that release of the segments from the central shank will permit withdrawing the shank from within the bore of the segments, and then the segments one at a time from within the bore 6 of the tube 4.

Preparatory setting-up of the machine

First, a set of four disk rollers 9 is selected, suitable to the diameter of the outside surface 5 of the tube 4 to be helically rolled, and mounted on the four spindles 14. Second, the tube guide bushing 13 is selected, having a bore 12 of the same diameter as the diameter of the outside surface 5 of the tube 4 to be helically rolled, and secured in the bore 99 of the split bearing 100 and bearing cap 101 of the tube guide bushing carriage 108. Third, the setting-up mandrel (not shown) is selected, having a circular cylindrical surface of the same diameter as the outside surface 5 of the tube 4 to be helically rolled and a length equal to the width of the pass 24 plus the length of the bore 12 of the tube guide bushing 13, and is forced into the bore 12 of the tube guide bushing 13, and rearwardly projecting from the bore 12 through the pass 24, by means of the carriage 108 in conjunction with the sleeve support bracket 132 and bore 130 in head 131 of the latter, similarly as explained in connection with mandrel locating and holding sleeve 95. Fourth, by individually rotating the four eccentric sleeves 18 the tube rolling faces 8 of the four disk rollers 9 are brought into contact with the setting-up mandrel within the pass 24, after which the eccentric sleeves 18 are clamped within their respective bores 25 in the spindle housing 26 in the manner described. Fifth, the setting-up mandrel is then removed from within the bore 12 of the tube guide bushing 13 by means of the carriage 108 and the bore 130 in head 131 of the sleeve support bracket 132, a bolt passing through a large washer on the forward side of the head 131 and screwed into a tapped hole in the forward end of the setting-up mandrel serving to hold the latter while the

carriage 108 is actuated rearwardly over the ways 109 by the actuating means described to pull the setting-up mandrel from within the bore 12. Sixth, the carriage 108 is then actuated over the 5 ways 109 in the rearward direction to hold the tube guide bushing 13 in the operative position as explained, and the carriage 108 is then locked in place on the ways 109 by means of pin 114. Seventh, the forward tubular blank guide bush- 10 ing 32 is selected, having bore 40 suitable for the diameter of the outside surface 2 of the tubular blank 1 from which the tube 4 is to be helically rolled, and secured in place within the central bore 36 and counterbore 38 in the spindle 15 housing 26 as explained. Eighth, the rear tubular blank guide bushing 57 is selected, having bore 66 suitable similarly as bore 40 of the bushing 32 in the seventh step, and secured in place within the bore 61 and counterbore 63 in the tubular 20 extension hub 49 as explained.

Operation of the machine with longitudinally stationarily held tube bore mandrels

First, the tube bore mandrel 11 is selected, 25 having the circular cylindrical outside surface 10 of the same diameter as that of the bore 6 of the tube 4 to be helically rolled, and a mandrel rod 88 of greater length than the tubular blank 1 from which the tube 4 is to be made, and placed 30 on the grooved rollers at the rear of the machine as explained and rolled into position in the machine, as seen in Fig. 7. Second, the mandrel locating and holding sleeve 95 is selected, having a circular cylindrical outside surface 97 and bore 94 of the same diameter as the outside 35 surface 5 and the bore 6 of the tube 4 respectively, and, with the mandrel rod 88 and the tube bore mandrel 11 securely held against endwise movement by means of the two retaining collars 40 89 at the rear end of mandrel rod 88 in engagement with the support bracket yoke 90, is forced 45 into place within the bore 12 of the tube guide bushing 13 and over the forward end extension of the outside surface 10 of the tube bore mandrel 11, by means of the actuation of the carriage 108 over the ways 109 and employing the bore 130 in the head 131 of the sleeve support bracket 132 as an abutment for the forward end hub 129 thereof as explained. The carriage 108 is then 50 locked in place on the ways 109 by means of the pin 114, with the tube guide bushing 13 in the operative position. Third, the support bracket 92 and yoke 90 are then actuated out of engagement with the retaining collars 89 at the rear 55 end of mandrel rod 88, to permit the tubular blank 1 to be passed over the mandrel rod 88 and into the machine in the forward direction until the forward end of the blank 1 is in contact with the conical faces 7 of the four disk rollers 9, the 60 grooved rollers at the rear of the machine facilitating handling of the tubular blank 1 and entering same into the machine. The support bracket 92 with yoke 90 is then again actuated to permit the yoke 90 to engage the two retaining collars 89 of the mandrel rod 88 65 and hold the latter coaxial to the longitudinal axis 23-23 of the pass 24, as seen in Fig. 7, the rear end of the blank 1 being clear of the collars 89. Fourth, pressure lubricant is then provided for the tube guide bushing 13 and the tube bore mandrel 11 and the four disk rollers 9, the lubricant being oil for cold worked tubes and water for hot worked tubes, as explained. Fifth, the operator then turns on the power to the electric motor 87, by means of an electric motor con-

trol switch (not shown), to cause the gear train to be rotatably driven and to rotatably drive the four spindles 14 and the four disk rollers 9 thereby, as explained in the description of Fig. 1. Rotation of the four disk rollers 9 causes the 5 conical faces 7 thereof to frictionally grip the outside surface 2 at the forward end of the blank 1 and to simultaneously rotate the blank 1 about the longitudinal axis 23-23 of the pass 24 and to feed same longitudinally forward into 10 the pass 24 into contact with the tube rolling faces 8, as seen at the start of the tube rolling operation in Fig. 9, so that the conical faces 7 and the tube rolling faces 8 thereafter jointly frictionally grip the outside surface 2 of the blank 15 1 and cause the latter to be simultaneously rotated about the longitudinal axis 23-23 of the pass 24 and to feed same longitudinally forward through the pass 24. As the rotation and feeding of the blank 1 proceeds, and simultaneously 20 therewith, the material of the walls of the tubular blank 1 is progressively compressively helically rolled within the pass 24 between the tube rolling faces 8 of the four disk rollers 9 and the outside surface 10 of the tube bore mandrel 11 25 (within the bore 3 of the blank 1, and held against endwise movement by the yoke 90 of the support bracket 92, as explained) until the entire length of the blank 1 has been helically rolled to form the tube 4. The initial phase of 30 the tube rolling operation is seen in Fig. 9, with the forward end of the blank 1 (and of tube 4) in contact with the rear end of the mandrel locating and holding sleeve 95, as displacement of the latter from within the bore 12 of the tube guide 35 bushing 13 and from over the forward end extension of the outside surface 10 of the tube bore mandrel 11 begins. The progressive displacement of the mandrel locating and holding sleeve 95 is seen in Fig. 13, and the condition after displacement is seen in Fig. 7, with the results already fully described. At the end of the tube rolling operation on the blank 1, the rear end of the tube 4 is even with the rear end of the bore 12 of the tube guide bushing 13, and other 40 successive blanks 1 may then be helically rolled without employing the mandrel locating and holding sleeve 95, the successive tubes 4 displacing one another from within the bore 12 of the tube guide bushing 13 and from over the outside 45 surface 10 of the forward end extension of the tube bore mandrel 11 successively, and serving to locate and hold the tube bore mandrel 11 longitudinally coaxially within the pass 24 in the same manner as the mandrel locating and holding sleeve 95. The procedure in removing the tube 4 from within the bore 12 of the tube guide bushing 13 and from over the forward end extension of the outside surface 10 of the tube bore mandrel 11, is to clamp a hinged split collar over 50 the outside surface 5 of the tube 4 at the forward end of the tube guide bushing 13 and then actuate the carriage 108 forwardly over the ways 109 to withdraw the bore 6 of the tube 4 from the mandrel 11, the hinged split collar (not shown) is next clamped onto the outside surface 5 of the tube 4 at the forward end of the bore 130 in the head 131 of the sleeve support bracket 132 and the carriage 108 actuated over the ways 109 in the rearward direction to withdraw the 55 outside surface 5 of the tube 4 from within the bore 12 of the tube guide bushing 13. The tube 4 is supported on the series of grooved rollers at the front end of the machine, as explained. For the greatest accuracy, the mandrel locating 60

and holding sleeve 95 should be employed frequently during the course of production of a lot of tubes 4, in order to insure the coaxial relation of the tube bore mandrel 11 within the pass 24, 5 as the rolling of one defective blank 1, having walls too thin, would serve to destroy this required relation of the mandrel 11 within the pass 24 and would result in rolling very imperfect tubes 4. When a number of passes of the tube 4 10 through the machine must be made to reduce either the diameter of the outside surface 5 of the tube 4 alone, or both the diameter of the outside surface 5 and that of the bore 6 as well, the setting-up of the machine must be repeated as 15 outlined for each such pass.

Operation of the machine with longitudinally movable tube bore mandrels

First, the tube bore mandrel 202, seen in Figs. 20 25-26-27, is selected, having the desired character of the outside surface 203 and diameter to suit the bore 6 of the tube 4 to be helically rolled, and is placed on the grooved rollers at the rear of the machine as explained and is rolled 25 into position in the machine with the shank 204 within the bore 12 of the tube guide bushing 13. Second, the mandrel locating and holding sleeve 205 is selected, having a circular cylindrical outside surface 206 of the same diameter as the outside surface 5 of the tube 4, and, with the rear end of the mandrel 202 abutting against the forward side of a steel block of H shape fitting the yoke 90 of the support bracket 92 to prevent rearward movement of the mandrel 202, while same 30 is forced into place within the bore 12 of the tube guide bushing 13 and over the shank 204 of the mandrel 202, by means of the carriage 108 actuated respectively forwardly over the ways 109 and employing a mandrel (not shown) fitting 35 within the bore 130 in head 131 of the sleeve support bracket 132 and having a rearwardly projecting enlarged head against which the forward end of sleeve 205 abuts to force the latter into bore 12, and actuated rearwardly to force 40 the latter over the shank 204. The mandrel just mentioned in bore 130 is then removed. With the tube guide bushing 13 in the operative position, the carriage 108 is then locked in place on the ways 109 by means of pin 114. Third, the 45 support bracket 92 with yoke 90 are then actuated downward out of the way below the grooved rollers at the rear of the machine, to permit the tubular blank 1 to be passed over the tube bore mandrel 202 and into the machine in 50 the forward direction over the grooved rollers with the forward end of the blank 1 finally in contact with the conical faces 7 of the four disk rollers 9. Fourth, pressure lubricant is turned on to supply only the tube guide bushing 13 55 and the four disk rollers 9, none being needed for the mandrel 202, the lubricant used being oil for cold worked tubes and water for hot worked tubes as explained. Fifth, by means of the electric control switch (not shown), the operator 60 starts the electric motor 87 to cause the gear train to rotatably drive the four spindles 14 and the four disk rollers 9, as explained in the description of Fig. 1. Rotation of the four disk rollers 9 causes the conical faces 7 thereof to frictionally 65 grip the outside surface 2 of the forward end of blank 1 and to simultaneously rotate the blank 1 together with the tube bore mandrel 202 and shank 204 about the longitudinal axis 23-23 of the pass 24 and to feed the blank 1 and mandrel 70 202 and shank 204 longitudinally forward until 75 202 and shank 204 longitudinally forward until

the outside surface 2 of the blank 1 is brought into contact with the tube rolling faces 8, similarly as at the start of the tube rolling operation with the stationarily held type of tube bore mandrel 11 seen in Fig. 9, so that the conical faces 7 and the tube rolling faces 8 thereafter jointly frictionally grip the outside surface 2 of the blank 1 and cause the blank 1 and the tube bore mandrel 202 within the bore 3 of blank 1 to be simultaneously rotated together about the longitudinal axis 23—23 of the pass 24 and to be fed longitudinally forward through the pass 24 as a unit. As the rotation and feeding of the assembly of the blank 1 and tube bore mandrel 202 proceeds, and simultaneously therewith, the material of the walls of the blank 1 is progressively compressively helically rolled within the pass 24 between the tube rolling faces 8 of the four disk rollers 9 and the outside surface 203 of the tube bore mandrel 202 until the entire 10 length of the blank 1 has been helically rolled to form the tube 4. In this instance, the shank 204 rotates with and is fed forward simultaneously with the formation of the tube 4, but the mandrel locating and holding sleeve 205 is 15 displaced only from within the bore 12 of the tube guide bushing 13 and remains in place on the shank 204. The displacement of sleeve 205 is due to both the shoulder formed by the junction of the shank 204 with the forward end of the 20 tube bore mandrel 202 and to the forward end of the tube 4. The function of the sleeve 205 is otherwise identical with the sleeve 95 employed with the longitudinally stationarily held tube bore mandrel 11 previously described, and the 25 tube 4 over the tube bore mandrel 202 within the bore 12 of the tube guide bushing 13 together serve in the same capacity as the tube 4 over the forward end extension of the outside surface 10 of the tube bore mandrel 11 within the bore 12 30 of the tube guide bushing 13, and, therefore, the outside surface 5 and the bore 6 of the tube 4 in this instance are produced longitudinally coaxial to each other for the entire length of the tube 4 as when the longitudinally stationarily held tube bore mandrel 11 is employed. The 35 different phases of the tube rolling operation, in this case, are very similar to those shown in Figs. 9—13—7, for the longitudinally stationarily held tube bore mandrel 11. At the end of the 40 tube rolling operation on the blank 1, the rear end of the tube 4 is even with the rear end of the bore 12 of the tube guide bushing 13, and the tube 4 together with the tube bore mandrel 202 are then withdrawn from within the bore 12 45 of the tube guide bushing 13, by moving the carriage 108 over the ways 109 until the forward end of the split bearing 100 and bearing cap 101 abut against the rear end of the bore 130 in the head 131 of the sleeve support bracket 132, and then 50 clamping the hinged split collar (not shown, the same as for the mandrel 11) over the outside surface 5 of the tube 4 at the forward end of the bore 130 in the head 131 of the sleeve support bracket 132, and, by actuating the carriage 108 over the ways 109 in the rearward direction the tube 4, together with the mandrel 202 within the bore 6 of the tube 4, are withdrawn from the bore 12 of the tube guide bushing 13, both being 55 supported by the series of grooved rollers at the front end of the machine. The tube 4 must then be stripped from the tube bore mandrel 202 in a tube stripping machine as in the past. The entire procedure must be repeated for each tube 4 60 as outlined. When the outside surface 5 of the tube 4 is 65

tube 4 must be reduced in diameter, a smaller diameter mandrel locating and holding sleeve 205 must be used for each successive pass through the machine, and the machine must, of course, be reset to suit each pass as already described, but the tube 4 need not be stripped from the tube bore mandrel 202 until the finishing pass has been made.

With both types of tube bore mandrels, the treatment of the tubular blank 4, and of the tube 4, with regard to annealing, pickling in acid baths, neutralizing in alkaline baths, and washing in hot water, for the usual purposes, must be observed as in the past procedure of manufacturing seamless tubes.

In Fig. 28 is shown a disk roller machine for planetarily cross rolling seamless tubes, in which the disk rollers 207 and the spindles 208 upon which these are rigidly removably mounted as shown, are not directly rotatably driven as before seen in the disk roller machine of Fig. 1, but in which the spindle housing 209 is rotatably mounted and rotatably driven to rotate about the longitudinal axis 210—210 of the pass of the disk rollers 207, causing the disk rollers 207 and their individual spindles 208 to rotate as the tube rolling faces 211 of the disk rollers 207 are made to planetarily roll over the outside surface 212 of the tubular blank 213 within the pass and to successively rollably follow each other within the same narrow lateral roller path. The longitudinal axes 214 respectively of the disk rollers 207 and their individual spindles 208, and bores 217 of the eccentric sleeves 216 in which the spindles 208 are rotatably mounted in suitable bearings, are each individually eccentrically located with respect to and parallel with the longitudinal axes 214 and 215' of the individual eccentric sleeves 216 and the laterally equally spaced bores 218 in spindle housing 209 in which the eccentric sleeves 216 are rotatably mounted. The axes 214 and 215' in turn are individually parallel to the axis 210—210 of the pass of the narrow square faces 211 of the disk rollers 207 laterally equally spaced at the forward end of the rotatable spindle housing 209. The spindle housing 209 is mounted to rotate in a forward and a rear bearing coaxial with longitudinal axis 210—210 of the pass. The forward bearing 219 consists of a large diameter roller bearing cage with horizontal rollers fitting rollably over an inner race coaxially attached to the outside circular cylindrical surface of the forward end of the spindle housing 209 and within an outer race attached coaxially within the bore of the forward bearing pedestal 220 attached to the machine base 221. The rear bearing 222 consists of a ball bearing of the usual kind, adapted to sustain both radial and thrust loading, with the outer race thereof coaxially attached within the bore of the hub of the main drive gear 223 integral with an end plate casting 224 coaxially attached as shown to the rear end of the spindle housing 209 and rotating therewith, and the inner race thereof coaxially attached over the forwardly projecting tubular boss of the rear bearing pedestal 225 and held stationary thereon; the pedestal 225 being rigidly attached to the machine base 221. A forward carriage base 226 and a rear carriage base 227, respectively forward and to the rear of the spindle housing 209, are each attached to the machine base 221, and are each provided with a pair of ways 228 and 229 respectively on their upper portions parallel to the longitudinal axis 210—210 of the pass. A blank guide bushing 230 is pro-

vided for guiding the tubular blank 213 coaxially with the pass, and is coaxially attached as shown within the bore of the tubular boss of the pedestal 225, extending coaxially forward through the central bore of the spindle housing 209 up to the rear sides of the disk rollers 207. The main drive gear 223 for rotatably driving the spindle housing 209 is in turn rotatably driven by the pinion 231 meshing therewith on the shaft 232 cooperably connected to a gear train rotatably driven in turn by an electric motor (not shown), during the tube rolling operation on the blank 213. The tube guide bushing 233 is rigidly removably mounted in a split bearing 234 on a carriage 235 reciprocably actuatable over the ways 228 of the forward carriage base 226 by suitable actuating means (not shown). The bore 238 of the tube guide bushing 233 is longitudinally coaxially forwardly adjacent to the pass of the disk rollers 207 during the tube rolling operation on the tubular blank 213, the carriage 235 being locked in fixed position on the ways 228 by means of removable lock pin 239 (similarly as seen before with reference to carriage 108 in Fig. 1). The sleeve support bracket 240, employed in connection with the mandrel locating and holding sleeve 241, for the same purpose as the support bracket head 131 seen in Fig. 1, is pivotally mounted coaxially forward of the bore 238 of the tube guide bushing 233 in a horizontal pivot bracket 242 attached to the side of the forward carriage base 226, and is adapted to be swung upward out of the way when not in use. A forward chuck 243 and a rear chuck 244, each coaxial with the longitudinal axis 210—210 of the pass, are non-rotatably rigidly mounted respectively on forward chuck carriage 245 and on rear chuck carriage 246 reciprocably actuatable as required by suitable actuating means (not shown) over the ways 228 and 229 respectively of the forward carriage base 226 and of the rear carriage base 227. The rear chuck 244 is adapted to grip the rear end of the blank 213 and push feed same longitudinally forward through the pass during the tube rolling operation on same, while simultaneously preventing any rotation of the same. The forward chuck 243 is adapted to grip the forward end of the tube 249 as the latter emerges from the forward end of the bore 238 of the tube guide bushing 233, after the mandrel locating sleeve 241 (identical with sleeve 95 seen in Figs. 10-11) has been completely displaced from bore 238 in the same manner as for the sleeve 95 previously described in the description of the disk roller machine seen in Fig. 1, and to hold same against rotation while simultaneously pull feeding same in unison with the push feeding of same by the rear chuck 244, until the rear chuck 244 is necessarily released to permit rolling the rear end portion of the blank 213 still within the bore of the blank guide bushing 230. The actuating means (not shown) for the two chuck carriages 245 and 246 are adapted to actuate these individually or in unison to suit the above described operating conditions. The two retaining collars 250 having the hexagon supporting shank 251 therebetween, at the rear end of the mandrel rod 252, and the stationary type tube bore mandrel 253 provided with forward and rear conical ends, are identical with like named parts of the tube bore mandrel 11 seen in Figs. 1-7-9-13. The two retaining collars 250 with hexagon shank 251 engage the yoke 254 integral with mandrel rod carriage 255 during the tube rolling operation, for holding the 75

5 tube bore mandrel 253 against any endwise movement or rotation within the pass and within the bore 238 of the tube guide bushing 233, the yoke 254 being coaxial with the longitudinal axis 210—210 of the pass. The mandrel rod carriage 255 is slidably mounted on the two ways 229 of the rear carriage base 227 to the rear of the rear chuck carriage 246, and is adapted to be reciprocably actuated thereover as required by suitable 10 actuating means (not shown), and to be locked in fixed position thereon as required by suitable locking means (not shown) during the tube rolling operation on blank 213. The mandrel rod 252 passes through the central bore of the rear 15 chuck 244 and forward through the bore of the blank 213 as shown, to permit unrestricted free movement of the rear chuck 244 and the carriage 246 as required. When rolling thin walled tubes, the forward end of the blank in each instance is 20 cupped, and the forward end of the mandrel together with the mandrel locating and holding sleeve are modified as shown in Fig. 30 and later to be described, for both the stationary type and the longitudinally movable type mandrels; the 25 push feed by the rear chuck 244 and its carriage 246 in this instance is dispensed with, and the pull feed by the forward chuck 243 (suitably modified) and its carriage 245 is alone employed. While the stationary type mandrel 253 is shown 30 for rolling the blank 213, the longitudinally movable type mandrel 202 seen in Figs. 25—26—27 may likewise be employed, the operation in the latter case of course involving the forward movement of the mandrel 202 along with the blank 213 by the chucks 244 and 243 and their respective carriages 246 and 245, while the use of the yoke 254 and its carriage 255 is dispensed with. Adjustment of the disk rollers 207 is made by means of the eccentric sleeves 216, in the same manner 35 as for the machine seen in Fig. 1; the disk rollers 207 are likewise provided in sets, having the same diameters and widths for a given set adapted to roll a given range of outside surface diameters of tubes, and a plurality of such sets is 40 provided to cover the full diameter capacity range of the machine, similarly as for the machine seen in Fig. 1. The setting-up mandrel (not shown), as previously described for the machine seen in Fig. 1, is also employed for setting-up the disk rollers 207 for rolling particular tubes.

In Fig. 29 is shown another disk roller machine for planetarily cross rolling seamless tubes, somewhat similarly as seen with the machine shown 55 in Fig. 28. Parts here shown, where identical to those seen in Fig. 28, have been given the same numerals. In this instance, the rotatable spindle housing 209 with the therein mounted eccentric sleeves 216 and spindles 208 with attached disk rollers 207, as before described in connection with the description of Fig. 28, is mounted in the forward bearing 219 and the rear bearing 222 respectively in forward bearing pedestal 220 and rear bearing pedestal 225 attached to the top surface of the machine carriage 258. The machine carriage 258 is reciprocably actuated as required by suitable actuating means (not shown) over two longitudinal ways 262 of the machine base 263 parallel to the longitudinal axis 210—210 of the pass of the tube rolling faces 211 of the disk rollers 207. The spindle housing 209 is rotatably mounted in bearings 219 and 222 to rotate about the longitudinal axis 210—210 of the 60 pass, the same as in Fig. 28. The tube guide

bushing 233 is rigidly removably mounted in a split bearing 234 on bearing pedestal 264 attached to the top surface of the machine carriage 258, with the bore 238 thereof longitudinally coaxially adjacent to the pass of the disk rollers 207. The main drive gear 223 is attached to the spindle housing 209, as before described, for rotatably driving the latter, and is in turn rotatably driven by means of pinion 265 meshing therewith slidably splined to drive shaft 266. The pinion 265 has a coaxial sleeve extension 268 at one end thereof rotatably mounted in bearing 269 of pedestal 270 attached to the top surface of the machine carriage 258, so that pinion 265 is moved along with the carriage 258. The drive shaft 266 is held in position and rotatably mounted in the bearings 267 attached to machine base 263, and is parallel to the two ways 262; the gear 271 attached at the forward end thereof for rotatably driving same is in turn rotatably driven by a connected gear train rotatably driven by an electric motor (not shown). Thus, the spindle housing 209 is rotatably driven as the machine carriage 258 is actuated over the ways 262 from the forward end to the rear end 25 of the latter, to cause the tube rolling faces 211 of the disk rollers 207 to progressively planetarily rollably pass over the outside surface 212 of the blank 213 non-rotatably stationarily held within the pass by means of the forward chuck 243 and 30 the rear chuck 244 each coaxial with the longitudinal axis 210—210 of the pass. The rear blank-gripping chuck 244 is rigidly mounted on rear chuck carriage 246 reciprocably actuated as required by suitable actuating means (not shown) 35 over the two ways 229 parallel to the axis 210—210 of the pass to the rear of the machine carriage 258 on ways 262, and is adapted to grip the rear end of the blank 213 and hold same 40 against rotation and endwise movement with carriage 246 locked in fixed position on ways 229 by suitable locking means (not shown). The forward tube-gripping chuck 243 is rigidly mounted on forward chuck carriage 245 reciprocably actuated as required by suitable actuating means (not shown) 45 over the two ways 228 forward of the machine carriage 258 on ways 262, and is adapted to grip the forward end of the tube 249 as it emerges from the forward end of the bore 238 of the tube guide bushing 233 and to hold same 50 against rotation and endwise movement with carriage 245 locked in fixed position on ways 228 by suitable locking means (not shown). The rear blank-gripping chuck 244 is released from the rear end of the blank 213, and the rear chuck 55 carriage 246 is actuated rearward over the ways 229 out of the way of the machine carriage 258, in order to permit rolling the rear end portion of the blank 213. The two retaining collars 250 having the hexagon supporting shank 251 there- 60 between, at the rear end of the mandrel rod 252, and the stationary type tube bore mandrel 253 provided with forward and rear conical ends, are identical with like named parts of the tube bore mandrel 11 seen in Figs. 1—7—9—13. The two retaining collars 250 with hexagon shank 251 engage the yoke 254 integral with mandrel rod carriage 255 and coaxial with the axis 210—210 of the pass, the carriage 255 being reciprocably actuated as required by suitable actuating means 65 (not shown) over the two ways 229 to the rear of the rear chuck carriage 246, for the purpose of holding the tube bore mandrel 253 against rotation and simultaneously pull feeding same longitudinally rearwardly in unison with the rear- 70 75

ward movement of the machine carriage 258 over ways 262 during the tube rolling operation, so that the tube bore mandrel 253 is maintained in position within the pass and within the bore 238 of the tube guide bushing 233 throughout the tube rolling operation. The mandrel rod 252 passes through the central bore of the rear chuck 244 and forward through the bore of the blank 213 as shown, to permit unrestricted free movement of the mandrel rod 252, the yoke 254, and the mandrel rod carriage 255 as required. The mandrel locating and holding sleeve 241 is entered into bore 238 of the tube guide bushing 233 and over the extension of tube bore mandrel 253 by means of the sleeve support bracket 240 (together with the carriage 258), in the same manner as the sleeve 95 in conjunction with the support bracket head 131 seen in Fig. 1, and is employed for the same purpose and is similar to mandrel locating and holding sleeve 95 seen in Figs. 10-11. The sleeve 241 is here seen being displaced from within the bore 238 of the tube guide bushing 233 and from over the extension of the tube bore mandrel 253 by the tube 249, just prior to gripping of the forward end of the tube 249 by the forward chuck 243. The sleeve support bracket 240 is mounted forward of the two ways 262, coaxial with axis 210-210 when in the operating position, on a horizontal pivot bracket 242 attached to machine base 263, and is adapted to be swung upward out of the way when not in use. As with the machine seen in Fig. 28, when rolling thin walled tubes, the forward end of the blank in each instance is cupped, and the forward end of the mandrel together with the mandrel locating and holding sleeve are modified as shown in Fig. 30 and later to be described, for both the stationary type and the longitudinally movable type mandrels (not movable in this instance, but merely full-length mandrel). While the stationary type mandrel 253 is shown for rolling the blank 213, the longitudinally movable type mandrel 202 seen in Figs. 25-26-27 may likewise be used, the operation in the latter case being similar as for the stationary mandrel 253, except that the mandrel 202 is held fixed along with the blank 213 by the rear chuck 244 and forward chuck 243, while the use of the yoke 254 and its carriage 255 is dispensed with. Adjustment of the disk rollers 207 by means of the eccentric sleeves 216, the provision of sets of disk rollers 207, and the provision of the setting-up mandrel, are the same as for the machine in Fig. 28.

In Fig. 30 are shown the modifications of the stationary type mandrel required when such a mandrel is employed for rolling cupped-end tubular blanks in the disk roller machines seen in Figs. 28-29. As before stated, the blanks are provided with cupped ends, when these are not suited to ordinary rolling operations thereon, due to having walls too thin to sustain any severe strains thereon, such as thrust loading, and which may be found through the use of the stationary type and the longitudinally movable type tube bore mandrels of the construction previously described for these machines. The tubular blank 274 has the forward end thereof provided with swaged cupped-end 275, having coaxial hole 276 therein fitting tightly over the forwardly extending threaded sleeve 277 which in turn is fitted tightly coaxially over the forwardly extending coaxial shank 278 of the tube bore mandrel 279. The enlarged coaxial rear end collar 280 on the threaded sleeve 277, within the bore of blank

274 and abutting against the inner side of cupped-end 275, is of the same lateral form and dimensions as the tube bore mandrel 279, and abuts against the latter at the beginning of the tube rolling operation but departs from contact with the latter after the forward end extension of tube bore mandrel 279 is wholly within the bore 238 of the tube guide bushing 233 as shown. The cupped-end 275 of the blank 274 is clamped in place on threaded sleeve 277 between the forward side of collar 280 and the rear end of the mandrel locating and holding sleeve 281 having threaded bore 282 screwed onto threaded portion of the threaded sleeve 277 as shown. The construction shown, for the stationary type tube bore mandrel 279, is likewise applicable for the longitudinally movable type tube bore mandrel 202 seen in Figs. 25-26-27 for rolling cupped-end blanks 274 in the machines seen in Figs. 28-29; the forward end of the threaded sleeve 277 beyond the mandrel locating and holding sleeve 281 is gripped by forward chuck 243 (modified to suit) for pull feeding the blank 274 in the machine of Fig. 28, or for holding the blank 274 against all movement in the machine of Fig. 29 when the stationary type tube bore mandrel 279 is used; while for the longitudinally movable type tube bore mandrel 202 (modified as indicated above), the forward end of the shank 278 beyond the sleeve 277 is gripped by the forward chuck 243 (modified to suit) for pull feeding the blank 274 together with the mandrel 202 in the machine of Fig. 28, or for holding the blank 274 together with the mandrel 202 against all movement in the machine of Fig. 29; it being understood, as before explained, that the tube bore mandrel 279 (being of the stationary type) is held against all movement relative to the pass in both machines seen in Figs. 28-29. In the machine of Fig. 28, the forward chuck 243 pull feeds the blank 274 forward through the pass, the tube bore mandrel 279 moving forward along with the tube 274 into the bore 238 of the tube guide bushing 233 until same is wholly therein as shown and further movement thereof is prevented by the rear retaining collar 283 engaging the yoke 254 on the carriage 255, the latter being locked in place on the ways 229 as before described. The two retaining collars 283 at each end of the hexagon supporting shank 284 on the rear end of mandrel rod 285, are suitably spaced to permit the desired movement of mandrel 279 just described, the total movement of course being such as to allow the cupped-end 275 to be located to the rear of the disk rollers 207 at the beginning of the tube rolling operation. In the machine of Fig. 29 the forward chuck 243 holds the blank 274 (and later the tube 274') against all movement as the machine carriage 258 is actuated rearwardly over the ways 262, the tube bore mandrel 279 being likewise held against all movement along with the blank 274 and tube 274', so that the mandrel 279 along with tube 274' enters the bore 238 of the tube guide bushing 233 and continues until the mandrel 279 is wholly within the bore 238 as shown, whereupon the rear retaining collar 283 engages the yoke 254 on carriage 255 and movement of the mandrel 279 relative to the pass and the bore 238 ceases, and the mandrel 279, by means of the movement of the yoke 254 and carriage 255 in unison with the movement of the machine carriage 258, is maintained in this position as shown throughout the remainder of the tube rolling operation; the spacing of the collars 283 being the same as for the machine of

Fig. 28 to permit the movement of mandrel 279 just described, it being understood that the yoke 254 on carriage 255 is started in its movement in unison with carriage 258 at the start of the tube 5 rolling operation; the tube 274' is meanwhile held against all movement by the forward chuck 243 as before described until the whole blank 274 has been rolled. The rear chuck 244 on carriage 246 may, or may not, be used in connection with 10 rolling the cupped-end blanks 274 over the stationary type mandrel 279 in the machines of Figs. 28-29, depending upon the thickness of wall of the blanks 274, but is used for rolling the blanks 274 over the longitudinally movable mandrel 202 15 (modified as indicated) in these machines. In order to prevent any misalignment of the mandrel 279 from the required coaxial relation to the axis 210-210 of the pass of the disk rollers 207, due to sagging of the long mandrel rod 285, or 20 other causes, a universal joint 279' connection is made between the mandrel rod 285 and the tube bore mandrel 279 as shown, the universal joint 279' in this instance consisting of two yokes integral with mandrel rod 285 connected by means 25 of the usual four trunnion cross part to the two yokes integral with the rear end of the mandrel 279 as seen. This universal joint 279' is obviously applicable to all stationary type tube bore mandrels 11, 253, and 279 in equal measure, as 30 before mentioned in connection with the description of Fig. 16, for the purpose above described.

Where not shown or described in detail specifically, it is to be understood that all parts of the 35 machines seen in Figs. 28-29, where required to perform like or similar functions as those more fully shown in the drawings and described in complete detail with reference to the disk roller machine seen in Fig. 1, are intended by me to be the same as the parts in the machine seen in Fig. 1. Thus, the following details of the machines in Figs. 1-28-29, where not otherwise stated to be different, are to be considered to be the same: the disk rollers, in sets of different diameters to suit the diameter tubes to be rolled within the machine capacities, as well as in widths of tube rolling and conical faces thereof; the forward ends of the spindles, and the means for rigidly removably mounting the disk rollers thereon; 45 the eccentric sleeves, provided with bearings therein in which the spindles are rotatably mounted; thrust washers between the disk rollers and the forward ends of the eccentric sleeves; worm gears integral with the eccentric sleeves, 50 in meshing engagement with rotatably mounted manually rotatable worms, for rotating the eccentric sleeves while making radial adjustments of the disk rollers; the tube guide bushing, rigidly removably mounted in a split bearing; the tube 55 guide bushing carriage and reciprocating actuating means therefor; the blank guide bushing, removably mounted in the spindle housing; the stationary and the longitudinally movable types of tube bore mandrels; the mandrel locating and holding sleeves for the two types of tube bore 60 mandrels; the setting-up mandrels, for setting the disk rollers for rolling different diameters of tubes; and the sleeve support bracket, used in forcing the mandrel locating and holding sleeves 65 and the setting-up mandrels into the bore of the tube guide bushing as required; and the means for lubricating or cooling the tube bore mandrels, tube guide bushing bore, and the tube surfaces. 70

In Fig. 31 is shown the application of the positively controlled tube bore mandrel of my in-

vention to a tube drawing bench; only the essential affected parts thereof being seen, other parts, of the usual construction, not being shown. The tube guide bushing 286 is located forwardly adjacent to the drawing die 287, and is held in 5 fixed position therewith in the drawing head 288. The bore 289 of tube guide bushing 286 is coaxial with the longitudinal axis 306-306 of the die opening or pass of the die 287, and has the same lateral form and dimensions as the pass 10 in the die 287 and the outside surface of the tube 290, the latter having a cylindrical form of circular or non-circular section laterally of the bore and outside surface as required. The stationary type tube bore mandrel 291, having the same 15 lateral form and dimensions as the cylindrical bore of the tube 290 as described, is employed for drawing the majority of the tubes in the tube drawing bench, conforming to the practice formerly followed with the floating type tube bore 20 mandrels of the same stationary type. Where special non-cylindrical bores in the tubes 290 are required, the longitudinally movable type tube bore mandrel 202, seen in Figs. 25-26-27, 25 may be modified to have the forward end thereof of the same as that of mandrels 279 and 291, for drawing cupped-end blanks 292 to form such tubes. The tubular blank 292 has the forward end thereof provided with the swaged cupped-end 30 293, having coaxial hole 294 therein fitting 30 tightly over a forwardly extending threaded sleeve 295, which in turn is fitted tightly over the forwardly extending shank 296 of the tube bore mandrel 291. The enlarged rear end collar 297 on the threaded sleeve 295, within the bore of 35 blank 292 and abutting against the inner side of the cupped-end 293, is of the same lateral form and dimensions as the forward end of the tube bore mandrel 291 against which it abuts at the beginning of the tube drawing operation until the 40 tube bore mandrel 291 is drawn wholly within the bore 289 of the tube guide bushing 286 as shown. The cupped-end 293 is clamped in place on threaded sleeve 295 between the forward side of collar 297 and the rear end of the mandrel locating and holding sleeve 298 having threaded bore 299 screwed onto threaded sleeve 295 as 45 shown. The two retaining collars 300, at each end of hexagon shank 301 on the rear end of the mandrel rod 302 connected to the tube bore 50 mandrel 291, are spaced to allow the tube bore mandrel 291 to move longitudinally forward along with the blank 292 sufficiently to permit the tube bore mandrel 291 to enter wholly within the bore 289 of the tube guide bushing 286 as 55 shown, at which time the rear collar 300 comes into contact with the yoke 303 which prevents further movement of the tube bore mandrel 291. The yoke 303 is attached to the base of the tube draw bench in the usual manner at the required 60 distance from the die 287, and fits tightly over the hexagon shank 301 to maintain the latter coaxial to the longitudinal axis 306-306 of the pass of the die 287, as well as prevent any rotary or longitudinal movement of the mandrel 291 65 during the tube drawing operation. The gripping chuck 304, of the usual type, having jaws 305 for gripping the forward end of the threaded sleeve 295 beyond the mandrel locating and holding sleeve 298, is mounted on the usual chuck 70 carriage rollable over two longitudinal ways (not shown) of the machine base parallel to the axis 306-306 of the pass of the die 287, and is forwardly coaxial to the pass of the die 287, so that the tube 290 is pulled forward in the direction 75

indicated by the arrow coaxial with axis 306—306 of the pass of the die 287 during the tube drawing operation. The chuck carriage (not shown) is drawn forward over the machine ways by the 5 usual operably connected draw chain during the tube drawing operation, the draw chain in turn being operated by the usual mechanism.

In Fig. 32 is shown the application of the positively controlled tube bore mandrel of my invention to a tube rolling machine of the usual grooved roller type; only the essential affected parts thereof being shown, the other parts of the usual construction are omitted. The pair of rolls of the machine, comprising the top roll 15 307 and lower roll 308, having respectively annular grooves 309 and 310 therein opposite each other and of the same required radial section (semi-circular section here shown) to suit the outside surface of the tube 311 rolled from the 20 tubular blank 312, are rotatably driven in the usual manner to rotate about their longitudinal axes; the directions of rotation being as indicated by the curved arrows, to cause the blank 312 to be fed longitudinally forward as shown. The tube 25 guide bushing 313 is rigidly removably mounted in the split bearing 314 on carriage 315 reciprocably slidably mounted on two ways 316 on carriage base 317, and actuated by the same means seen for carriage 108 in the machine of Fig. 1, 30 parallel to the longitudinal axis 318—318 of the pass of the grooves 309 and 310 of the two rolls 307 and 308. The carriage 315 being locked in position on ways 316 by means of a lock pin (not shown) similar to lock pin 114 in Fig. 1, during 35 the tube rolling operation with tube guide bushing 313 in the operating position shown. The rear end of the tube guide bushing 313 is cut away to an approximate V shape to fit the forward side of the grooves 309 and 310 of the rolls 307 40 and 308. The bore 319 of the tube guide bushing 313, extending up to the dotted line 319' in the pass, is coaxial with the longitudinal axis 318—318 of the pass of the grooves 309 and 310 of the two rolls 307 and 308. The stationary type tube bore 45 mandrel 320 is provided with mandrel rod 321 having hexagon support 322 and retaining collar 323 at the rear end of the latter, for engaging the yoke 324 coaxial with longitudinal axis 318—318 of the pass of grooves 309 and 310 of the rolls 307 and 308. The mandrel 320 is located coaxial with axis 318—318 of the pass at 50 the beginning of the tube rolling operation by means of the mandrel locating and holding sleeve 325; the mandrel 320 and sleeve 325 are identical 55 respectively with the mandrel 11 and sleeve 95 employed in the machine in Fig. 1. The mandrel 202 and sleeve 205 seen in Figs. 25—26—27, for the machine in Fig. 1, may likewise be employed with this tube rolling machine, where it is desired to 60 employ the longitudinally movable type tube bore mandrel. The yoke 324 is attached to the machine base in the usual manner and located, to suit the length of blank 312 being rolled, either at the rear end (as shown) or at the forward 65 end of the machine as often is the case. With the yoke 324 located at the forward end of the machine, the mandrel rod 321 will occupy the position 321' shown dotted in the drawings, and there will have to be provided two retaining collars 323 with hexagon support 322 therebetween 70 for engaging yoke 324.

In Fig. 33 is shown the application of the positively controlled tube bore mandrel of my invention to a tube piercing and reeling mill, of the 75 so-called Stiefel type, and otherwise of the usual

construction, all non-essential details of the mill being omitted. The pair of rolls 326 and 327, having the usual forms as shown, are rotatably driven by the usual driving means to rotate as indicated by the arrows about their longitudinal axes, which are non-parallel and eccentric to each other as usual, to cause the billet 328 to be simultaneously rotated and fed longitudinally forward through the pass thereof and forced progressively over the piercing mandrel 329 to 10 form the tube 330. In reeling the pierced tube 330, the action is very similar to that of tube rolling, the piercing mandrel 329 being then replaced by a reeling mandrel (not shown), not having a pointed end as here shown, but of the 15 same form as the forward end of the mandrel 11 for the machine seen in Fig. 1, so that mandrel 11 may be used in this machine for the purpose, with the extension thereof similarly within the bore 331 of the tube guide bushing 332 as the 20 extension of the piercing mandrel 329 shown. The tube guide bushing 332 is rigidly removably mounted in the split bearing 333 on the carriage 334, and the latter is reciprocably slidably mounted on two ways 335 of the machine base 25 (not shown) and actuated, by similar means as are employed for the carriage 108 for the machine seen in Fig. 1, parallel to the longitudinal axis 336—336 of the pass, and is locked in position on the ways 335 by suitable means during 30 the tube piercing and reeling operations; the tube guide bushing 332 being in the operating position shown, with the bore 331 thereof coaxial with longitudinal axis 336—336 of the pass of the rolls 326 and 327. The rear end of the 35 tube guide bushing 332 is cut away at the rolls 326 and 327 to form notches 338, with projections 338 thereof extending rearwardly between the rolls 326 and 327 up to the dotted line in the pass, as shown in end view in Fig. 34; the projections 338 having a tapered entrance bore 339 to facilitate entrance of tube 330 into the bore 331 of bushing 332 (similarly as bore 193 for bushing 13 in Figs. 20—21—22). The piercing mandrel 329, and the reeling mandrel as described before (not shown), are located coaxial with the longitudinal axis 336—336 of the pass, at the beginning of the tube piercing operation and the tube reeling operation respectively, by means of the mandrel locating and holding sleeve 340, which is very similar to the sleeve 95 employed with the machine in Fig. 1. The mandrel rod 341 extends in the forward direction as seen, and is supported in the required coaxial relation to axis 336—336 at the forward end thereof in the usual manner by means similar to those seen in Fig. 35. For tube reeling, besides the stationary type mandrel 11 employing the sleeve 340 or sleeve 95 mentioned, the longitudinally movable tube bore mandrel 202 and sleeve 205 seen in Figs. 25—26—27, (for the machine in Fig. 1), may be employed in this machine.

In Fig. 35 is shown the application of the positively controlled tube bore mandrel of my invention to a tube piercing and reeling mill, of the so-called Mannesmann type, and otherwise of the usual construction, all non-essential details of the mill being omitted. The pair of rolls 342 and 343, having the usual form as shown, are 70 rotatably driven by the usual driving means to rotate as indicated by the arrows about their longitudinal axes, which are angular to each other and are non-intersecting as usual, to cause the billet 344 to be simultaneously rotated and fed 75

longitudinally forward through the pass thereof as indicated by the arrows and forced progressively over the piercing mandrel 345 to form the tube 346. In reeling the pierced tube 346, the 5 action is very similar to that of tube rolling, the piercing mandrel being then replaced by a reeling mandrel (not shown), not having a pointed end as here shown, but of the same form as the forward end of the mandrel 11 for the machine seen in Fig. 1, so that mandrel 11 may be used in this machine for the purpose, with the extension thereof similarly within the bore 347 of the tube guide bushing 348 as the extension of the piercing mandrel 345. The tube guide bushing 348 is 10 rigidly removably mounted in the split bearing 349 on the carriage 350, and the latter is reciprocably slidably mounted on two ways 351 of the machine base (not shown) and actuated thereover by similar means as are employed for the 15 carriage 108 for the machine seen in Fig. 1 parallel to the longitudinal axis 352—352 of the pass, and is locked in position on the ways 351 by suitable means during the tube piercing and reeling operations; the tube guide bushing 348 being shown in the operating position, with the 20 bore 347 thereof coaxial with the longitudinal axis 352—352 of the pass of the rolls 342 and 343. The rear end of the tube guide bushing 348 is cut away at the rolls 342 and 343 to form notches 25 353, with projections 354 thereof extending rearwardly between the rolls 342 and 343 up to the dotted line in the pass, as shown in the end view in Fig. 36, the projections 354 having a tapered entrance bore 355 to facilitate entrance of tube 346 into the bore 347 of tube guide bushing 348 (similarly as bore 193 for bushing 13 in Figs. 20—21—22). The piercing mandrel 345, and the reeling mandrel as described before (not shown), are located coaxial with the longitudinal axis 352—352 of the pass, at the beginning of the tube 30 piercing operation and the tube reeling operation respectively, by means of the mandrel locating and holding sleeve 356, which is very similar to the sleeve 95 employed with the machine in Fig. 1. The mandrel rod 357 extends in the forward direction as seen, and is supported in the required coaxial relation to axis 352—352 at the forward end thereof by the usual supporting bracket 358 attached to the ways 351 as shown. 35 For tube reeling, besides the stationary type mandrel 11 employing the sleeve 356 or sleeve 95 mentioned, the longitudinally movable tube bore mandrel 202 and sleeve 205, seen in Figs. 25—26—27 (for the machine in Fig. 1), may be employed 40 in this machine.

While the invention is susceptible of various modifications and alternative constructions, I have shown in the drawings and described in detail herein the preferred embodiment of my invention, though it will be understood that I do not thereby intend to limit the scope of the invention to the specific form disclosed, and that I aim to cover all other forms of the invention falling within the spirit and scope of the invention as expressed in the appended claims.

I claim as my invention:

1. In a tube forming machine of the described class, means for forming the outside surface of the tube arranged to compose a working pass, mandrel means for forming the bore of the said tube in the said pass, means for relatively feeding the blank from which the said tube is formed through the said pass during the tube forming operation, means coaxially adjacent to the said pass adapted to tightly coaxially contact with the

said outside surface of the said tube adjacent to the said pass and positively guide same coaxially with the said pass, means coaxially connected to the said mandrel means adapted to tightly coaxially contact with the said bore of the said tube adjacent to the said pass and positively guide same coaxially with the said mandrel means within the said pass, and means coaxially connected to the said mandrel means and the said bore guiding means and tightly coaxially contacting with the said outside surface guiding means adjacent to the said pass for positively locating and holding the said mandrel means and said bore guiding means coaxial to each other and respectively coaxial within the said pass and to the said outside surface guiding means at the start of the said tube forming operation, the said locating and holding means adapted to be longitudinally coaxially moved relatively to said outside surface guiding means and relatively away from said pass as the forward end portion of the said tube is formed to thereby cause the said outside surface and the said bore of the said forward end portion of the said tube to be formed coaxial to each other, and the part of the said forward end portion of the said tube progressively formed and adjacent to the said pass adapted in the same manner as the said locating and holding means thereafter for positively locating and holding the said mandrel means and the said bore guiding means coaxial to each other and respectively coaxial within the said pass and to the said outside surface guiding means as the remaining portion of the said tube is formed to thereby cause the said outside surface and the said bore of the said remaining portion of the said tube to be formed coaxial to each other.

2. In a tube forming machine of the described class, means for forming the outside surface of the tube arranged to compose a working pass, 40 mandrel means for forming the bore of the said tube in the said pass, means for relatively feeding the blank from which the said tube is formed through the said pass during the tube forming operation, means coaxially adjacent to the said pass adapted to tightly coaxially contact with the said outside surface of the said tube adjacent to the said pass and positively guide same coaxially with the said pass, means coaxially connected to the said mandrel means adapted to tightly coaxially contact with the said bore of the said tube adjacent to the said pass and positively guide same coaxially with the said mandrel means within the said pass, and means connected in the required axial relation to the said mandrel means and the said bore guiding means and tightly coaxially contacting with the said outside surface guiding means adjacent to the said pass for positively locating and holding the said mandrel means and the said bore guiding means coaxial to each other and respectively in the said required axial relation within the said pass and to the said outside surface guiding means at the start of the said tube forming operation, the said locating and holding means adapted to be longitudinally coaxially moved relatively to the said outside surface guiding means and relatively away from said pass as the forward end portion of the said tube is formed to thereby cause the said outside surface and the said bore of the 50 said forward end portion of the said tube to be formed in the said required axial relation to each other, and the part of the said forward end portion of the said tube progressively formed and adjacent to the said pass adapted in the same 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 manner as the said locating and holding means thereafter for positively locating and holding the said mandrel means and the said bore guiding means coaxial to each other and respectively in 5 the said required axial relation within the said pass and to the said outside surface guiding means as the remaining portion of the said tube is formed to thereby cause the said outside surface and the said bore of the said remaining portion 10 of the said tube to be formed in the said required axial relation to each other.

3. In a tube forming machine of the described class, means for forming the outside surface of the tube arranged to compose a working pass, 15 mandrel means for forming the bore of the said tube in the said pass during the tube forming operation, means for relatively feeding the blank from which the said tube is formed through the said pass during the said tube forming operation, 20 means coaxially adjacent to the said pass adapted to tightly coaxially contact with the said outside surface of the said tube adjacent to the said pass and positively guide same coaxially with the said pass, means coaxially connected to the said 25 mandrel means adapted to tightly coaxially contact with the said bore of the said tube adjacent to the said pass and positively guide same coaxially with the said pass, and means connected in the required axial 30 relation to the said mandrel means and the said bore guiding means and tightly coaxially contacting with the said outside surface guiding means adjacent to the said pass for positively locating and holding the said mandrel means and the said 35 bore guiding means coaxial to each other and respectively in the said required axial relation within the said pass and to the said outside surface guiding means at the start of the said tube forming operation, the said locating and holding means 40 adapted to be longitudinally coaxially moved relatively to the said outside surface guiding means and relatively away from said pass as the forward end portion of the said tube is formed to thereby cause the said outside surface and the 45 said bore of the said forward end portion of the said tube to be formed in the said required axial relation to each other, and the part of the said forward end portion of the said tube progressively 50 formed and adjacent to the said pass having the said outside surface and the said bore thereof respectively tightly coaxially contacting with the said outside surface guiding means and the said bore guiding means adapted thereafter for positively 55 locating and holding the said mandrel means and the said bore guiding means coaxial to each other and respectively in the said required axial relation within the said pass and to the said outside surface guiding means as the remaining portion of the said tube is formed to thereby cause the said outside surface and the 60 said bore of the said remaining portion of the said tube to be formed in the said required axial relation to each other.

4. In a tube forming machine of the described class, means for forming the outside surface of the tube arranged to compose a working pass, 65 mandrel means for forming the bore of the said tube in the said pass during the tube forming operation, means for relatively feeding the blank from which the said tube is formed through the 70 said pass during the said tube forming operation, means coaxially adjacent to the said pass adapted to tightly coaxially contact with the said outside surface of the said tube adjacent to the said 75 pass and positively guide same coaxially with the

said pass, means coaxially connected to the said mandrel means adapted to tightly coaxially contact with the said bore of the said tube adjacent to the said pass and positively guide same coaxially with the said mandrel means within the 5 said pass, and means coaxially connected to the said mandrel means and the said bore guiding means and tightly coaxially contacting with the said outside surface guiding means adjacent to the said pass for positively locating and holding the said mandrel means and the said bore guiding means coaxial to each other and respectively coaxial within the said pass and to the said outside surface guiding means at the start of the 10 said tube forming operation, the said locating and holding means adapted to be longitudinally coaxially moved relatively to the said outside surface guiding means and relatively away from said pass as the forward end portion of the said tube is formed to thereby cause the said outside surface and the said bore of the said forward end portion of the said tube to be formed coaxial to each other, and the part of the said forward end portion of the said tube progressively formed and adjacent to the said pass having the said outside surface and the said bore thereof respectively tightly coaxially contacting with the said outside surface guiding means and the said bore guiding means adapted thereafter for positively locating and holding the said mandrel means and the said bore guiding means coaxial to each other and respectively coaxial within the said pass and to the said outside surface guiding means as the remaining portion of the said tube is formed to thereby cause the said outside surface and the said bore of the said remaining portion of the said tube to be formed coaxial to each other.

5. In a tube forming machine of the described class as claimed in claim 4, wherein the said means are comprised in a disk roller machine for helically rolling tubes, and the said means and the said disk roller machine are substantially as set forth.

6. In a tube forming machine of the described class as claimed in claim 4, wherein the said means are comprised in a disk roller machine for cross rolling tubes, and the said means and the said disk roller machine are substantially as set forth.

7. In a tube forming machine of the described class as claimed in claim 4, wherein the said means are comprised in a tube drawing bench, and the said means and the said tube drawing bench are substantially as set forth.

8. In a tube forming machine of the described class as claimed in claim 4, wherein the said means are comprised in a grooved roll tube rolling machine, and the said means and the said grooved roll tube rolling machine are substantially as set forth.

9. In a tube forming machine of the described class as claimed in claim 4, wherein the said means are comprised in a tube piercing and reeling mill, and the said means and the said tube piercing and reeling mill are substantially as set forth.

10. In a disk roller machine for cross rolling tubes, a plurality of identical disk rollers radially and circumferentially equally spaced about a common point to compose a working pass, the said rollers rigidly removably coaxially mounted on one end of individual roller spindles to rotate therewith, the common longitudinal axes of the said rollers on said spindles individually equiangular to a plane perpendicular to the longi- 75

tudinal axis of said pass through said common point, the said spindles held against endwise movement and rotatably mounted in individual bearings in eccentrically located bores of individual eccentric sleeves, the said sleeves held against endwise movement and rotatably mounted in individual bores of a spindle housing, the said bores of the said housing similarly spaced and the longitudinal axes thereof similarly equi-angularly disposed to respectively the said common point and the said plane as the said rollers on said spindles, the longitudinal axes of said bearings in said bores and of the outside surface of each of said sleeves parallel to each other and having equal eccentricities to allow an equal individual range of adjustment of said rollers radially relative to the said longitudinal axis of said pass when said sleeves are rotated in said bores of said housing while making equal radial adjustments of said rollers to suit the diameter of the outside surface of the tube to be rolled, the said range of adjustment of said rollers allowing said rollers to roll tubes having outside surface diameters lying within the diameter capacity range thereof, means individually connected to said sleeves for manually rotating same individually in said bores of said housing for making said radial adjustments of said rollers independently of one another, means for holding said sleeves against relative movement in said bores of said housing individually after said radial adjustments of said rollers have been made, connected rotatably driving means for causing the said rollers and said spindles to be rotated and the said rollers to rollably relatively pass over the outside surface of the blank from which the tube is rolled while cross rolling same during the tube rolling operation thereon, mandrel means for forming the bore of the said tube in the said pass during the said tube rolling operation, means for relatively longitudinally feeding the said blank through the said pass during the said tube rolling operation, means rearwardly coaxially adjacent to the said pass adapted at random to loosely contact with the said outside surface of the said blank and guide same coaxially with the said pass, means forwardly coaxially adjacent to the said pass adapted to tightly coaxially contact with the outside surface of the said tube adjacent to the said pass and positively guide same coaxially with the said pass, means coaxially connected to the said mandrel means adapted to tightly coaxially contact with the said bore of the said tube adjacent to the said pass and positively guide same coaxially with the said mandrel means within the said pass, and means coaxially connected to the said mandrel means and the said bore guiding means and tightly coaxially contacting with the said outside surface guiding means adjacent to the said pass for positively locating and holding the said mandrel means and the said bore guiding means coaxial to each other and respectively coaxial within the said pass and to the said outside surface guiding means at the start of the said tube rolling operation, the said locating and holding means adapted to be longitudinally coaxially moved relatively to the said outside surface guiding means and relatively away from the said pass as the forward end portion of the said tube is rolled to thereby cause the said outside surface and the said bore of the said forward end portion of the said tube to be rolled coaxial to each other, and the part of the said forward end portion of the said tube progressively formed and adjacent to the said

pass adapted to serve thereafter in the same manner as the said locating and holding means as the remaining portion of the said tube is rolled.

11. In a tube forming machine of the described class as claimed in claim 4, wherein the said mandrel means and the said bore guiding means are rigidly coaxially connected to each other, the said outside surface guiding means consists of tube guide bushing means having a bore adapted to tightly coaxially contact with the said outside surface of the said tube adjacent to the said pass, and the said locating and holding means for the said mandrel means and the said bore guiding means consists of means removably connected to the latter two means and to the said bore of the said tube guide bushing means at the start of the said tube forming operation. 15

12. In a tube forming machine of the described class as claimed in claim 4, wherein the said mandrel means and the said bore guiding means are rigidly coaxially connected to each other and connected to mandrel rod means, the said outside surface guiding means consists of tube guide bushing means having a bore adapted to tightly coaxially contact with the said outside surface of the said tube adjacent to the said pass, the said tube guide bushing means rigidly removably mounted in bearing means for maintaining the said bore thereof coaxially adjacent to said pass during the said tube forming operation, the said bearing means for the said tube guide bushing means adapted to be rigidly held in fixed position relative the said pass during the said tube forming operation, the said mandrel rod means having connected supporting and retaining means at the end thereof opposite said mandrel means and said bore guiding means adapted to prevent rotation thereof and support same in alignment axially with said pass and to retain said mandrel means and said bore guiding means respectively in the required longitudinal relation to the said pass and the said bore of the said tube guide bushing means during the said tube forming operation, the said mandrel means and said bore guiding means replaceable by other similar means to suit the bores of other tubes similarly formed as said tube, the said tube guide bushing means replaceable by other similar means to suit the outside surfaces of other tubes similarly formed as said tube, and the said mandrel means and said bore guiding means and said tube guide bushing means provided with means for cooling and lubricating same during the said tube forming operation.

13. In a tube forming machine of the described class as claimed in claim 4, wherein the said mandrel means and the said bore guiding means are rigidly coaxially connected to each other and connected to mandrel rod means, the said outside surface guiding means consists of tube guide bushing means having a bore adapted to tightly coaxially contact with the said outside surface of the said tube adjacent to the said pass, the said tube guide bushing means rigidly removably mounted in bearing means for maintaining the said bore thereof coaxially adjacent to said pass during the said tube forming operation, the said bearing means for the said tube guide bushing means adapted to be rigidly held in fixed position relative the said pass during the said tube forming operation, the said mandrel rod means having connected supporting and retaining means at the end thereof opposite said mandrel means and said bore guiding means adapted to prevent rotation thereof and support same in alignment axially with said pass and to retain said mandrel means and said bore guiding means respectively in the required longitudinal relation to the said pass and the said bore of the said tube guide bushing means during the said tube forming operation, the said mandrel means and said bore guiding means replaceable by other similar means to suit the bores of other tubes similarly formed as said tube, the said tube guide bushing means replaceable by other similar means to suit the outside surfaces of other tubes similarly formed as said tube, and the said mandrel means and said bore guiding means and said tube guide bushing means provided with means for cooling and lubricating same during the said tube forming operation.

13. In a tube forming machine of the described class as claimed in claim 4, wherein the said mandrel means and the said bore guiding means are rigidly coaxially connected to each other and connected by pivotal joint means to mandrel rod means, the said pivotal joint means allowing for inadvertent axial misalignment between the said mandrel rod means and the said mandrel means and said bore guiding means due principally to sagging of said mandrel rod means, the said outside surface guiding means consists of tube guide bushing means having a bore adapted to tightly coaxially contact with the said outside surface of the said tube adjacent to the said pass, the said mandrel rod means rigidly coaxially connected to hexagonal shank means between two retaining collar means at the end thereof opposite said pivotal joint means, and yoke means connected to the base of said machine adapted to engage said hexagonal shank means and said retaining collar means respectively for preventing rotation of and supporting said mandrel rod

- means in alignment axially with said pass and for retaining said mandrel means and said bore guiding means respectively in the required longitudinal relation to said pass and said bore of said tube guide bushing means during the said tube forming operation.
14. In a tube forming machine of the described class as claimed in claim 4, wherein the said machine consists of a tube drawing bench, the said tube outside surface forming means consists of a tube drawing die, the said pass consists of the die opening of said die, the said outside surface guiding means consists of tube guide bushing means having a bore adapted to tightly coaxially contact with the said outside surface of the said tube adjacent to the said die opening of said die, the said die and the said tube guide bushing means rigidly removably mounted together in the die head means of said tube drawing bench with the tube exit end of said die opening of said die adjacent to said bore of said tube guide bushing means and coaxial to each other, and the said blank provided with a cupped-end as shown and described.
15. In a tube forming machine of the described class as claimed in claim 4, wherein the said mandrel means and the said bore guiding means are rigidly coaxially connected to each other, the said mandrel means coaxially connected to one end of mandrel rod means, the said mandrel rod means rigidly coaxially connected to hexagonal shank means between two retaining collar means in spaced relation longitudinally at the end thereof opposite said mandrel means, the said bore guiding means adapted to form the said bore of the said forward end portion of the said tube at the start of said tube forming operation, the said outside surface guiding means consists of tube guide bushing means having a bore adapted to tightly coaxially contact with the said outside surface of said tube adjacent to said pass, the said tube guide bushing means rigidly removably mounted in bearing means adapted to maintain said bore thereof coaxially adjacent to said pass during said tube forming operation, the said blank of tubular form provided with a cupped-end having a forwardly projecting flange surrounding the smooth coaxial hole therein, the said locating and holding means consists of means tightly coaxially removably fitting within said bore of said tube guide bushing means and coaxially removably connected by interconnecting means to the forward end of said bore guiding means at the start of said tube forming operation, the said interconnecting means comprising clamping means for rigidly coaxially clamping the flanged-side of said cupped-end of said blank to the rear end of said locating and holding means during said tube forming operation and shank means adapted to coaxially connect said clamping means and said forward end of said bore guiding means within the bore of said blank at the start of said tube forming operation and to be disconnected between said clamping means and said forward end of said bore guiding means after the start of said tube forming operation, the said clamping means comprising shoulder means within said bore of said blank abutting against the inner side of said cupped-end rigidly coaxially connected to threaded means fitting tightly coaxially in said hole of said cupped-end and screwed tightly coaxially into a corresponding threaded bore of said locating and holding means fitting tightly coaxially over said flange and abutting against the said flanged-side of said cupped-end, the said shoulder means of said clamping means of the same

form and lateral dimensions as said forward end of said bore guiding means abutting against and comprising part of the latter means at the start of said tube forming operation, yoke means connected to the base of said machine adapted to engage the said hexagonal shank means of the said mandrel rod means for preventing rotation of said mandrel means and said bore guiding means and for supporting said mandrel rod means in axial alignment with said pass and to engage said two retaining collar means of said mandrel rod means one at a time for restricting the longitudinal movement of said mandrel means and said bore guiding means to the required amount relative to said pass and said bore of said tube guide bushing means while the said forward end portion of said tube is formed at the start of said tube forming operation, the said longitudinal movement of said mandrel means and said bore guiding means allowing said bore guiding means to form said bore of said forward end portion of said tube at the start of said tube forming operation, the said shoulder means of said clamping means departing from said forward end of said bore guiding means located at the forward end of said bore of said tube guide bushing means opposite said pass with said mandrel means within said pass and immovably held in fixed position and said shank means disconnected between said clamping means and said forward end of said bore guiding means after the start of said tube forming operation and said forward end portion of said tube has been formed, and the said blank feeding means consists of feeding means having connected chuck means adapted to be coaxially connected to said locating and holding means for longitudinally coaxially feeding said locating and holding means clamped to said cupped-end of said blank as a unit relative to said pass and said mandrel means and said bore guiding means for the said longitudinal movement thereof relative said pass and said bore of the said tube guide bushing means during the said tube forming operation.

16. In a disk roller machine as claimed in claim 10, wherein the said means for manually individually rotating the said eccentric sleeves within the said bores of the said housing consists of worm and worm gear means individually connected to the said eccentric sleeves, the said means for holding the said eccentric sleeves against rotary relative movement in said bores in said housing individually after said radial adjustments of said rollers have been made consists of individual set screw means screwed through the walls of said bores of said housing and abutting against said outside surfaces of said eccentric sleeves and of other individual set screw means screwed through the walls of the bearings of the shafts of said worm means and abutting against said shafts of the said worm means, and the said means for guiding the said blank coaxially with the said pass consists of blank guide bushing means removably mounted and held against rotation within the central bore of the said housing rearwardly coaxially adjacent to said pass, all substantially as set forth.

17. In a disk roller machine as claimed in claim 10, wherein the said outside surface guiding means consists of tube guide bushing means having a bore adapted to tightly coaxially contact with the said outside surface of the said tube adjacent to the said pass, the said mandrel means and the said bore guiding means are rigidly coaxially connected to each other, the said tube guide bushing means rigidly removably mounted

in split bearing means rigidly mounted on carriage means, the said carriage means slidably mounted on ways connected to the base of said machine, the said ways parallel to the said longitudinal axis of said pass to cause the said bore of said tube guide bushing means to remain coaxial with said pass on slidably moving said carriage means on said ways, means for locking said carriage means in fixed position on said ways 5 for holding said bearing means in fixed position and maintaining said bore of said tube guide bushing means coaxially adjacent said pass

during said tube forming operation, the said locating and holding means consists of sleeve means having eye-lever means and lug means as described, sleeve supporting means as described, means at the forward end of said bearing means 5 for locking and unlocking said sleeve means therein as described, and means connected to the said carriage means for reciprocably actuating said carriage means over said ways for the described purposes.

JOHN B. WINTERCORN. 10
